 Associated Electric Laboratories, Inc., Chi-
 cago, Ill., a corporation of Delaware

Application December 6, 1937, Serial No. 178,276

37 Claims. (Cl. 179—17)

The present invention relates to telephone systems and more particularly to power, switching and supervisory apparatus for use in small telephone exchanges of the automatic type.

The operating advantages of the automatic telephone exchange, as contrasted with the manual type of exchange, are well known in the art. Because of these advantages, the present trend in the installation of telephone systems favors the use of automatic equipment in any replacement or original installation irrespective of the size of the system. In the construction of exceedingly small exchanges for use in areas of limited population and usually designed to serve one hundred subscribers' lines or less, the problem of maintaining the manufacturing and installation costs below a prohibitive value without sacrificing reliability of operation is a very real one. This is particularly true in small exchanges which are entirely automatic in character, as contrasted with the well-known type of remotely controlled automatic exchange, for the reason that the auxiliary equipment included therein, namely, the power and supervisory apparatus, must necessarily be as complete and extensive as the corresponding apparatus used in larger installations. In the past, little attention has been directed to the possibilities of reducing the construction cost of the small automatic exchange through the expedient of simplifying the power and supervisory apparatus which forms a necessary adjunct of the line switching apparatus per se. On the contrary, it has been the practice to adopt more or less in toto the form of this apparatus as used in the larger exchanges, only minor alterations being made therein for the purpose of adapting the apparatus to the extensive operating requirements inherently present in the small automatic exchange. More specifically, it has been the prior practice to provide a separate and distinct unit for each individual supervisory function; i. e., separate units are provided for: generating coded ringing current for the selective energization of signalling devices associated with a called line of the party type; supervising the allotter means conventionally provided for switch link assignment purposes; supervising the line lock-out and link release apparatus usually embodied in each switch link; and other purposes. As a result, the element of cost represented by the power and supervisory apparatus is disproportionately large in prior exchanges of small size.

It is an object of the present invention, there-
 fore, to provide in an automatic telephone sys-

tem, improved and exceedingly simple apparatus for performing, in a thoroughly reliable manner, any and all of the functions ordinarily required in a small telephone exchange.

More specifically, it is an object of the invention to provide, in a telephone system of the character briefly referred to above, power and supervisory apparatus so arranged that the requisite functions of the apparatus are consolidated in a minimum number of circuit elements.

The invention as described in detail herein-after is illustrated in its embodiment in a small community automatic exchange designed to serve a plurality of subscribers' lines of the party line type and a group of two-way trunk lines interconnecting the community exchange with a main or central exchange of the manual type. Finder-connector links employing rotary switches are used exclusively for the line switching functions, allotter means being provided, in accordance with well-known practice, for assigning the links to successive calling lines in a definite order. Impulse responsive means are provided in the connector portion of each link through the operation of which the associated connector switch is caused to perform its line selecting functions in response to impulses transmitted thereto by way of a calling subscriber's line from a calling substation. In conformance with the use of party lines, namely, lines having more than one substation connected thereto, the power and supervisory apparatus is arranged for selective ringing over either side of a called line. Specifically, this apparatus includes a source of alternating ringing current, a plurality of ringing current conductors and means comprising a rotary interrupting switch for intermittently connecting the conductors to the source so that each thereof has impressed thereon the voltage of the source for coded intervals which are different for each of the lines.

In general, the objects as set forth above are in part attained in accordance with the present invention by assigning two or more functions to at least a portion of the elements involved in generating the interrupted ringing current. Thus, means controlled by the interrupter switch are provided for assigning a second link to search for a calling line in the event a first assigned link fails to find the said calling line; means controlled by the interrupter switch are provided for releasing a link seized by one of the lines and for preventing another link from being assigned to the line in the event the connector portion of the seized link is not caused to select

a called line within a predetermined time interval after the link is seized; and means controlled by the control means for the switch are provided for causing the connector portion of a seized link to 5 search for an idle one of the trunk lines on a call which is to be extended by way of one of the trunk lines. In accordance with a further feature of the invention, an improved arrangement is provided for applying, without interference, 10 ringing current to a calling line in the course of completing a desired connection on a reverting call, i. e., a call in which a subscriber having a telephone connected to one subscriber's line desires a connection with a telephone connected to 15 the same line. Further features of the invention pertain to the arrangement for checking the condition of the apparatus in the community exchange from a remote point, the arrangement for indicating an all-trunks-busy condition on 20 a trunk call to the distant manual exchange, and the particular arrangement of the circuit elements whereby the apparatus required is reduced to an absolute minimum.

The novel features believed to be characteristic of the invention are set forth with particularity in the appended claims. The invention itself, however, both as to its organization and method of operation, together with further objects and advantages thereof, will best be understood 25 by reference to the specification taken in connection with the accompanying drawings in which Figure 1 illustrates diagrammatically an automatic telephone system of the type to which the present invention is applicable; Fig. 2 illustrates the figure layout for the remaining figures of the drawings; Figs. 3, 4 and 5 illustrate the details of one of the finder-connector links incorporated in the system of Fig. 1; Fig. 6 illustrates the allotter means and a portion of the 30 power and supervisory apparatus embodied in the system; Fig. 7 illustrates the remaining portion of the power and supervisory apparatus; Figs. 8 and 9 illustrate a two-way repeater terminating one of the trunk lines of the system; 35 and Fig. 10 illustrates the apparatus terminating the opposite end of the trunk line extending to the repeater illustrated in Figs. 8 and 9.

Referring now more particularly to Fig. 1 of the drawings, the system there shown comprises 40 a small community exchange 10 and a manual exchange 12 interconnected by a group of trunk lines, one of which is indicated in the drawings as terminating at a two-way repeater circuit 20 forming a part of the apparatus located at the 45 exchange 10. Also extending to the exchange 10 are a plurality of subscribers' lines, two of which are indicated at 11 and 16 having connected thereto the subscribers' substations A and B. The subscribers' lines may be either of 50 the two-conductor type or of the well-known grounded type employing but a single conductor, or both. With the arrangement described in detail hereinafter, all grounded lines are equipped with adapters in order to permit the desired 55 switching and signalling functions to be successfully carried out. Although each of the two lines shown is illustrated as having only one telephone substation connected thereto, it is contemplated that a plurality of substations will be 60 connected to each line or, in other words, that each subscriber's line will be of the party type. Each of the substations connected to the various 65 subscribers' lines may comprise the usual hand set having embodied therein a dial controlled 70 impulsive device of conventional arrangement.

Each of the lines extending to the exchange 10 terminates in a line circuit through which it is rendered accessible to the finder portions of the finder-connector links included in the exchange, and by way of which it is terminated in the banks of the connector portions of the various links. Thus, the line 11 terminates at the line circuit 21 through which it is connected to the bank contacts of a connector switch 22 forming a part of the finder-connector link 23 and by way 1 of which it is rendered accessible to the finder portion 24 of the link 23. Similarly, the line 16 terminates at the line circuit 25 and the illustrated two-way trunk interconnecting the exchanges 10 and 12 terminates at the repeater 20 1 connected to the line circuit 387.

The exchange 10 is designed to serve only a small number of subscribers' lines, specifically nineteen, and a small group of three trunk lines and, accordingly, all of the subscribers' lines and 21 trunk lines are arranged to be served by any one of the plurality of finder-connector links included therein. Obviously, the number of links required for satisfactory service will depend upon the volume of telephone traffic, but, taking into 26 account the character of the exchange, four links are considered adequate for reasonably good service. In order to assign the links to successive calling lines in a definite order so that a link 30 is always available for use by a calling line, excepting, of course, those instances when all of the links are simultaneously busy, there is provided allotter means as indicated at 27. This allotter means is suitably interconnected with each of the links, each line circuit, and also with 35 the power and supervisory apparatus indicated at 28. The power and supervisory apparatus is interconnected with each of the links in the manner indicated.

Neglecting for the present the details of the 40 circuit arrangement, the system as briefly described above is in general quite similar to conventional systems, the operation of which is well understood in the art. In brief, when a subscriber, such, for example, as the subscriber at 45 the telephone A, initiates a call over the line 11 to a second subscriber's telephone, such, for example, as the telephone B, by lifting his receiver from its hook, the line circuit 21 causes the allotter means 27 to the calling line to be started 50 in operation to search for and seize the calling line. Assuming that the link 23 is delegated by the allotter means 27 to set up the connection, the finder portion 24 of the link operates to 55 select the calling line and to connect it through to the conductors of the link line incoming to the connector portion of the link. When the calling line 11 is seized and extended by way of the finder switch to the associated connector switch, the control equipment of the last-mentioned 60 switch is automatically conditioned to be responsive to the first series of impulses transmitted from the impulsive device at the substation A.

In response to the dialing of the first digit at 65 the calling substation, the connector switch 22 is caused to operate in a novel manner to select the group of lines including the called line 16. Thereafter, and in response to the dialing of the second digit, the called line 16 is selected from the selected 70 group of lines. When the called line is selected, the control apparatus included in the link circuit 23 functions to test the condition of this line, thereby to determine the busy or idle condition thereof.

If the called line is found busy, busy-tone current generated by a portion of the power and supervisory apparatus 28 is applied to the loop extending to the calling subscriber's substation, 5 thereby to indicate to the calling party that the desired connection can not immediately be completed. If, on the other hand, the called line is idle at the time it is selected, the calling subscriber may proceed to dial the third and final 10 digit for the purpose of selecting ringing current of the particular code which corresponds to the called substation B connected to the line 16. At the conclusion of this digit, the control apparatus embodied in the link circuit 23 functions to apply 15 the selected coded ringing current to a selected side of the line 16, thereby to energize the signalling device at the substation B in accordance with the code identifying this substation. During 20 the ringing operation, ring-back tone current is applied to the loop extending to the calling subscriber's substation to indicate to the calling party that the desired substation is being signalled. Finally a connection between the calling and called lines is completed when the call is 25 answered at the substation B. As pointed out with particularity hereinafter, the arrangement of the link circuit is such that a link utilized in setting up a desired connection is released only when the connection is cleared out at the calling 30 substation.

The switching apparatus located in the exchange 10 is also utilized in setting up a connection between two substations connected to the same line, the sole function of the apparatus in 35 this regard being that of selecting and applying ringing current to the calling line of the proper code to signal the called party. The discharge of this function necessitates the seizure of the calling line by an idle link and the operation of the 40 connector portion of the link to select the calling line, all in the manner outlined above. Thereafter, and following the dialing of the ringing current code selecting digit at the calling substation, the calling party restores his receiver to its hook 45 and ringing current of the selected code identifying the called substation is projected over the calling line. When the call is answered, the operated link is released and the line circuit of the line in service operates to busy the line and thereby 50 prevent its seizure by the connector portion of another link on a subsequent call. Finally the line circuit of the line is restored to normal when the connection is cleared out.

In the operation of the link to select one of the 55 small group of trunk lines outgoing from the exchange 10 and extending to the exchange 12, only two predetermined digits are required to cause the connector portion of the link to select the group of trunk lines. At the conclusion of 60 these two digits and, in accordance with one feature of the present invention, certain of the elements embodied in the link circuit 23 cooperate with a portion of the equipment in the power and supervisory apparatus 28 to cause the connector 65 switch 22 to operate in the manner of a trunk-hunting selector switch. Immediately the series of impulses comprising the second digit is concluded, this last-mentioned apparatus is started into operation to cause the connector switch 22 70 to search for an idle one of the selected group of trunk lines. When an idle trunk line is found, the trunk-hunting operation is interrupted and the calling line is extended by way of the selected trunk line and the associated two-way repeater 75 circuit to the terminating apparatus located at

the distant exchange 12. In this connection, it is noted that two sets of link line conductors are provided in the link circuit 23, one of which is devoid of all voice frequency coupling elements, such, for example, as condensers, and is utilized in 5 extending a desired connection by way of one of the trunk lines. Following the extension of the connection to the trunk line terminating apparatus located in the exchange 12, the connection may further be extended to the desired called line 10 through the intervention of an operator in the manner conventionally followed in manual exchange operation. Following the establishment of a connection in the above-described manner, the release of the connection is entirely under 15 the control of the operator in the exchange 12.

Since the trunk lines interconnecting the exchanges 10 and 12 are of the two-way type, it follows that any one of these lines and the switching apparatus included in the exchange 10 may 20 be utilized in the completion of calls originating or extending by way of the exchange 12 and which are to be extended to one of the subscribers' lines terminating at the exchange 10. The mode of operation of the equipment in the exchange 10, 25 following the extension of a call thereto by way of one of the trunk lines noted, is exactly the same as that set forth above with reference to the connection established between the substations A and B, it being observed that each of these trunk 30 lines terminates in a line circuit identical with that associated with each of the subscribers' lines. Here again the release of the connection is entirely under the control of the intervening operator 35 who originates the call in the exchange 12.

Considering now in greater detail the apparatus embodied in the exchange 10 and involved in the above-described sequence of operations, and referring more particularly to the apparatus illustrated in Figs. 3, 4 and 5, there are illustrated the 40 elements of the line circuit 21 terminating the subscriber's line 11, and the finder-connector link 23. The line circuit comprises a line relay R310, a cut-off relay R320, and a line lock-out relay R300, all arranged in accordance with conventional practice. This circuit also includes a condenser 305 through which pay-station tone current may be applied to the control conductor C394 of the line 11 from an alternating current source, not shown, for purposes referred to specifically hereinafter. This pay-station tone circuit is shown in association with the line 11 for illustrative purposes only, it being pointed out that a circuit of this form is provided only in association with those of the lines terminating at 55 the exchange 10 having telephones of the pay-station type connected thereto. Since the apparatus for applying pay-station tone current to the conductor C394 may be entirely conventional in character, an illustration thereof is omitted. 60

The line circuits respectively associated with each of the other lines extending to the exchange 10 are identical with that terminating the line 11, and, hence, that terminating the trunk line 100 and indicated at 387 is only diagrammatically 65 illustrated.

The finder portion of the link 23 comprises the stepping switch 380 and the line switching relay R350. The switch 380 is of the standard rotary type and comprises three sets of bank contacts 70 384, 385, and 386, of twenty-five points each, wipers 381, 382 and 383 respectively associated with the contact sets 384, 385 and 386, and means comprising the motor magnet M330 and a ratchet and pawl mechanism, not shown, for driving the 75

- enumerated wipers over the contacts of their respective associated sets. The connector portion of the link similarly includes a rotary switch 550 of standard construction which comprises bank contact sets 551, 552, 553, 554 and 555, wipers 581, 582, 583, 584 and 585 respectively associated with the contact sets in the order of their enumeration, and means comprising the motor magnet M540 and a ratchet and pawl mechanism, not shown, for driving the wipers over the contacts of their respective associated contact sets. As regards the connector portion of the link, the conductors of the lines extending to the exchange 10 are terminated at the contacts of the sets 551 and 552 of the switch 550 and the private or control conductors of these lines extend to the contacts of the set 553. Specifically, the subscribers' lines are divided into two groups comprising ten lines and nine lines, respectively. The lines of the ten-line group are connected to the contacts numbered from three to twelve of the indicated contact sets while the lines of the nine-line group are connected to the contacts numbered from fourteen to twenty-two. The contacts corresponding to the twenty-third, twenty-fourth, and twenty-fifth off-normal positions of the switch are reserved for terminating the conductors of the three trunk lines interconnecting the exchange 10 with the exchange 12.
- Also included in the link circuit is a ringing current code selector switch 560. This switch, which is of the well-known minor type, includes two sets of bank contacts 561 and 562, wipers 563 and 564 respectively associated with the contact sets 561 and 562, means comprising the motor magnet M565 and a ratchet and pawl mechanism, not shown, for driving the enumerated wipers over their respective associated contacts, a release magnet M566 operative to restore the switch to normal, and a set of off-normal springs 570 for controlling certain of the relays referred to hereinafter. The switch 560 has terminating in its upper set of bank contacts, in the manner indicated, five ringing current conductors C154 to C158, inclusive, which lead to the power and supervisory apparatus illustrated in Fig. 7 by way of the cable 150.
- Although the particular arrangement of the control relays will best be understood by reference to the detailed description of the operation which follows, it is believed that a brief reference to the functions performed by certain combinations of these relays will facilitate an understanding of the features of the circuit to which the present invention relates. In this connection, it is pointed out that R370 is the usual line relay which responds to impulses transmitted over a calling line to the link circuit; R403 is the usual hold relay for holding the finder portion of the link operated following the seizure thereof and during impulsing; R410 is a relay which operates to repeat impulses transmitted to R370; R420 is a slave relay controlled by R403; and that these four relays, in combination with the circuits controlled thereby, comprise impulse responsive means for causing the connector switch 550 to select any desired subscriber's line or the group of trunk lines terminating at the exchange and for causing the code selector switch 560 to select a desired ringing current conductor for connection to the selected line. Transfer of the impulsing circuit from the magnet M540 of the switch 550 to the magnet M565 of the code selector switch 560 is a function assigned to R490, which relay operates at the end of the second digit dialed at a

calling substation and is directly controlled by R460 and R450. Testing of a called line selected by the connector portion of the link to determine its idle or busy condition is achieved through the provision of the busy relay R470, the operating circuit for this relay being held prepared during second digit impulsing by means comprising the relay R450. The application of ringing current to a selected called line is an assigned function of the ringing relay R520, this relay in turn being controlled by the interrelated operation of R490 and the code selector switch 560. As pointed out in detail hereinafter, the selection of a particular ringing code and the proper application of ringing current to a selected called line is tantamount to the selection of one of the group of ringing current conductors C154 to C158, inclusive, and the connection of this selected conductor to project ringing current over only one side of the selected line, ground return ringing being utilized throughout.

The interruption of the ringing operation when a called substation on a selected called line answers is accomplished in the usual manner through the operation of R520, which relay will be recognized as the conventional ring cut-off relay. The operation of this relay also results in the completion of a talking loop to the called subscriber's substation and in the completion of a circuit including this loop for energizing the supervisory relay R400. The last-mentioned relay is a slave relay which controls the energization of the battery reversing relay R360. This battery reversing relay performs the usual function of reversing the polarity of the direct potential applied to the loop extending to a calling subscriber's substation for metering or other supervisory purposes.

In order to adapt the link circuit for efficient ringing during the establishing of a reverting call and for additional purposes pointed out herein-after, there are provided two additional relays R430 and R350. The first of these relays is energized only in the course of completing a reverting call and functions to control R350, which latter relay is a switching relay effective to switch the line conductors of the calling line from a connection with the set of link line conductors C104 and C108 to a connection with the set of link line conductors C105 and C109. The purpose of thus switching the conductors of a calling line to C105 and C109 on a reverting call is to remove the winding of R400 from across the ringing circuit thereby to prevent this winding from shunting a substantial portion of the ring-ing current during the ringing operation.

A further function of R350 is that of switching the conductors of a calling line, in the manner noted, in the course of completing a connection extending by way of one of the trunk lines 60 interconnecting the exchange 10 and the exchange 12 so that the voice coupling condensers 388 and 399 are removed from the loop circuit. In this case the operation of the switching relay R350 is under the control of R500 which latter relay also enters into the trunk-hunting operation of the rotary switch 550 during the movement of the switch to select an idle outgoing trunk line.

As pointed out in the introductory portion of the specification, one feature of the invention is concerned with the provision of means for locking out a calling line in the event a connection is not established to a desired called line within a predetermined time interval after the seizure 75

of one of the links. Specifically, this means comprises, in addition to portions of the power and supervisory apparatus illustrated in Fig. 7, the relay R440 and the line and lockout relays, such, for example, as the relays R320 and R300, embodied in the line circuit 21.

In order to adapt the link circuit illustrated for use in connection with lines of the grounded type, i. e., lines including a single line conductor 10 and a ground return path, there is provided, in addition to the apparatus already mentioned, the relay R510 which functions to control certain of the relays in the link circuit only in the event a line of the grounded type is selected.

15 In order to remove the finder-connector link from service for purposes of repair or testing, there is included therein the manually operable switch 385. This switch is normally maintained in the position shown in the drawings but, when 20 operated to its off-normal position, functions in a conventional manner to mark the link as busy in the allotter means, thereby to prevent the link from being assigned for use.

Referring now more particularly to the allotter 25 means as illustrated in Fig. 6, this means comprises, in brief, a rotary switch 670, a link start relay R610, a hold relay R605, an impulsive relay R620, a link transfer relay R625, and an all-links-busy relay R600. The switch 670 is of the 30 standard rotary type and includes four sets of bank contacts 675 to 678, inclusive, wipers 671 to 674 respectively associated with the bank contact sets in the order of their enumeration and means comprising a ratchet and pawl mechanism, not shown, and a motor magnet M660 for driving the wipers step by step over the contacts of their respective associated contact sets. As indicated above, this allotter means is arranged to control the selection of an idle link 40 from a group of four links, the various control conductors being terminated in the bank contacts of the switch 670 in the manner illustrated. As will be apparent from the detailed description which follows, the mode of operation of the allotter means is more or less conventional in form 45 as regards its function to select idle ones of the associated links. It is noted, however, that the manner in which the link transfer relay R625 cooperates with certain of the elements embodied in the power and supervisory apparatus, to assign 50 a second link to a calling line upon failure of a first assigned link to find the line, departs from conventional practice and forms the subject matter of one feature of the present invention.

55 The power and supervisory apparatus which is illustrated in the lower portion of Fig. 6 and in Fig. 7 comprises, in brief, a source of ringing current in the form of a mechanical inverter shown in the lower left-hand portion of Fig. 6, the five ringing current conductors C154 to C158, inclusive, and means comprising the rotary switch 710 for intermittently connecting these conductors to the ringing current source so that each thereof has impressed thereon the voltage of this source for coded intervals which are different for each of the conductors. The last-mentioned means also comprises the control means for the switch 71, which control means specifically includes the relays R107, R710, R715 and R720. Also arranged to be controlled by the four relays noted are the self-restoring relays R700 and R705 which comprise respectively a source of busy-tone current and a source of dial tone current. The 70 four relays forming the control means for the 75

switch 770 also function to control the two relays R650 and R655, which latter relays, in combination with R500 or a corresponding relay embodied in another of the links, comprise means for causing the connector portion of a seized link 5 to select an idle trunk outgoing from the exchange 10 on a call which is to be completed by way of one of these trunks.

The switch 770 not only functions as a 10 ringing current interrupter switch but, in addition, forms an integral part of a timing unit for applying supervisory ground pulses to the three supervisory conductors C137, C135 and C148. This unit includes, in addition to the switch noted, the four cyclically operating relays R724, R730, R735 and R740. The arrangement is such that the ringing apparatus is utilized for alarm purposes for indicating to a supervisory substation the condition of the equipment in the exchange 10. To this end the 20 three relays R750, R755 and R760 are embodied in the power and supervisory apparatus, which relays control, in accordance with the condition of the equipment, the characteristic of the voltage applied to the alarm conductor C152 and 25 utilized for checking the condition of the equipment from a remote point.

The two-way repeater illustrated in Figs. 8 and 9 associated with one of the trunk lines interconnecting the exchanges 10 and 12 and the apparatus terminating this trunk line in the exchange 12, as illustrated in Fig. 10, are of more or less conventional arrangement. Since this portion of the system is illustrated primarily for the purpose of insuring a complete disclosure 35 with reference to the operation of the equipment located in the exchange 10, it is thought that a detailed consideration of the various elements included therein is unnecessary at this point in the description, the function of these elements 40 being pointed out with particularity in the following description. All of the relays included in this equipment, as well as the relays specifically mentioned above, are illustrated in accordance with well-defined conventions to indicate 45 the particular operating characteristics possessed thereby.

Operation of the finder switch to seize the calling line

Referring now more particularly to the operation of the apparatus located in the rural office 10 to establish a connection between the lines 11 and 16 on a call from the suboffice A to the substation B and assuming that the link illustrated 55 in Figs. 3 to 5, inclusive, is the link delegated by the allotter means shown in Fig. 6 to set up the connection, the operation of this link is initiated when the calling party at the substation A removes his receiver from its hook to complete the 60 usual subscriber's loop circuit for energizing the line relay R310. The circuit noted extends from ground at RA322 by way of the lower winding of R310, C393, the direct current bridge across C393 and C392 at the substation A, C392, RA321 and 65 through the upper winding of R310 to battery. The relay R310 upon operating applies, at RA312 and RC313, ground to the control conductor C394, thereby to mark the calling line 11 as busy in the bank contacts of the connector switches 70 to which this line extends. At RA315, the relay R310 marks the calling line in the bank contacts of the rotary finder switch 380 by applying battery through the cut-off relay R320 by way of RA304, RA315 and C393' to the contact in the 75

contact set 386 which corresponds to the calling line. At RA811, the relay R810 applies ground to the start conductor C124 to start the finder portion of the link in operation to search for and 5 seize the calling line.

Thus, when ground is applied to C124, a circuit is completed for energizing R810 in series with the multiply connected motor magnets M660 and M540. In this connection it is pointed out that, 10 with any one of the several links embodied in the office 10 idle, R600 is in an energized condition so that the above-noted circuit for R810 is completed immediately upon the operation of the line relay R810 or any other line relay. This 15 circuit extends from ground on C124 by way of RA602 and the winding of R810 where it divides, one branch extending by way of RA601, MA661 and the winding of M660 to battery, and the other branch extending by way of RA612, C133, 20 the switch wiper 671, C138, RA346, RC348, the switch springs 386 and 387, C128, RA428, C118, RA359, C121, RA465, RA487, RC489', C186, MA542 and through the winding of M540 to battery. Due to the resistance of the winding of 25 R810, the two magnets noted, namely, M660 and M540, are not sufficiently energized to attract their associated armatures and, hence, remain inactive. The relay R810, however, operates to interrupt, at RA612, a point in the above-traced 30 branch of the circuit described which extends to M540. At RA616 the relay R810 prepares a circuit, traced hereinafter, for energizing R625 and, at its armature RA618, it completes a circuit extending by way of RC615 for energizing R805. 35 The operation of R810 also results in the energization of the motor magnet M330 embodied in the rotary switch 388 over a circuit extending from ground at RA618 by way of RC615, RA621, C131, the switch wiper 674, C126, RA343 and 40 through the winding of M330 to battery. At RA617, the relay R810 applies multiple ground to C128, thereby to maintain R600 operated independently of the condition of the other links embodied in the office 10. At RA611, the relay R810 45 completes a circuit for energizing the upper winding of R370, this circuit extending from ground at RA611 by way of the resistor 691, C134, the switch wiper 672, C129 and through the upper winding of R370 to battery. 50 The relay R370 operates when its upper winding is energized, and completes, at RA371, a circuit for energizing R410, this circuit extending from ground at RA407 by way of RC409, C113, RA371, C111 and through the winding of R410 to 55 battery. At RA372, the relay R370 prepares a holding circuit for R403. The operating circuit for the last-mentioned relay is completed upon the operation of R410 and extends from ground at RA412 by way of RC413, C115, and the winding of R403 to battery. The relay R410 upon 60 operating also completes a holding circuit for itself, this circuit extending from ground at RA411 by way of the resistor 445, C113, RA371, C111 and the winding of R410 to battery. 65 The relay R403, upon operating, similarly completes, at RA407, the above-noted holding circuit for itself, which circuit extends from ground at RA407 by way of RC408, C116, RA372, RC373, C115 and through the winding of R403 to battery. The relay R403 further completes, at 70 RA405 and RA406, a circuit for energizing R420, this circuit extending from ground at RA442 by way of RA406, RA405, and the winding of R420 to battery. At RA406, the relay R403 also pre-

pares a holding circuit, traced hereinafter, for the switching relay R340.

The relay R428 upon operating prepares, at its armatures RA421 and RA428, holding circuits for certain of the relays specifically referred to hereinafter. When R428 operates it also removes, at RA421, ground from the conductor C125 thereby to open one of the multiple holding circuits for R600 embodied in the allotter. The relay R428, upon operating, further completes, at RA427, a 10 circuit for energizing the relay R720 embodied in the power and supervisory apparatus illustrated in Fig. 7, this circuit extending from ground at RA427 by way of the start conductor C122 and through the winding of R720 to battery. 15

When R605 operates substantially simultaneously with the operation of R810, it prepares at RA608 a circuit, traced hereinafter, for energizing M660 and, at RA609, completes an obvious multiple holding circuit for R600. At RA608, the 20 relay R605 extends ground through the upper winding of R620 and the switch wiper 673 to the test conductor C127, thereby to provide a path over which the upper winding of the switching relay R340 may be energized when the wipers of 25 the rotary switch 388 are subsequently stepped to a position corresponding to the calling line 11.

The magnet M330, upon being energized in response to the operation of R810, attracts RA381 to complete a circuit extending by way of C128 30 for energizing the lower winding of R620. The relay R620, in turn, operates to interrupt, at RA621, the above-traced circuit for M330. The magnet M330 now restores to step the associated switch wipers 381, 382 and 383 one step and to 35 interrupt, at RA381, the operating circuit for R620. The relay R620 again restores to recomplete the operating circuit for M330. This inter-related operation of M330 and R620 continues until such time as the wipers of the switch 388 40 are stepped to a position corresponding to the calling line 11. In the present assumed case, wherein the control conductor C388' extends to the third contact of the contact set 386, the switch 388 is caused to take three steps from the 45 position shown in the drawings, at which time the switch wiper 383 engages its associated third contact to complete a circuit for energizing the upper winding of R340. This circuit extends from battery at the cut-off relay R320 by way of RA304, RA315, C393', the switch wiper 383, the upper winding of R340, C127, the switch wiper 673, C132 and through the upper winding of R620 to ground at RA608. Since the upper winding of R620 is now being energized over a 50 circuit which is independent of M330, this relay stays operated to hold open the operating circuit for M330. As a result, the interrelated operation of this relay and M330 is discontinued. When the upper winding of R340 is energized over the above-noted circuit, this relay partially 55 operates to complete, at RA344, a circuit for energizing its lower winding, this latter circuit extending from ground at RA442 by way of RA406, C110, RA344, and the lower winding of R340 to 60 battery. With its lower winding energized, R340 completes its operation to interrupt, at RA343, a further point in the operating circuit for M330 and to complete, at RA345, a circuit for energizing the cut-off relay R320 associated with the 65 calling line 11. At RA346, the relay R340 completes a circuit for energizing M660, thereby to cause the allotter means to operate in the manner pointed out hereinafter to a position corresponding to the next idle link.

The above-noted circuit for energizing the cut-off relay R320 extends from ground at RA442 by way of RA406, C110, RA344, RA345, the switch wiper 383, C393', RA315, RA304 and through the 5 winding of R320 to battery. This relay, upon operating, short circuits, at RA326, the armatures RA315 and RA304 thereby to provide a holding circuit for itself and, at its armatures RA321 and RA322, interrupts the above-traced operating 10 circuit for the line relay R310. The last-mentioned relay, upon restoring, removes, at RA311, ground from the start conductor C124; opens, at RA315, the marking path as traced above; and completes, at RA312 and RC314, an alternative 15 path for applying ground to the control conductor C394 from the ground extended to C393'. At RA322, the cut-off relay, upon operating, completes an obvious circuit for energizing the slow-to-release line lockout relay R300, which latter 20 relay now operates to open a further point in the path for applying ground to the start conductor C124 and a further point in the path for marking the calling line in the bank contacts of the rotary switch 380.

25 Immediately upon the operation of the switching relay R340, the subscriber's loop incoming from the calling substation A is extended by way of RA341 and RA342 to the link line conductors C104 and C108. The extension of this loop to 30 these conductors results in the completion of an alternative operating circuit for R370, which circuit extends from ground at the lower winding of this relay by way of the said lower winding, RA364, RC356, RA355, RA342, the switch wiper 382, C393, the bridge across C393 and C932 at 35 the substation A, C392, the switch wiper 381, RA341, RA352, RC353, RA362 and through the upper winding of R370 to battery. With the subscriber's loop thus extended and the relays R300, 40 R320, R340, R370, R403, R410 and R420 operated, the connector portion of the link is conditioned to respond to impulses transmitted thereto from the impulsive device conventionally provided at the calling substation A.

45 *Operation of the allotter means to find an idle link*

Before describing the operation of the link during the transmission of impulses thereto from the calling subscriber's substation, the operation 50 of the allotter means illustrated in Fig. 6 will be considered. In this connection, it will be noted that a busy link is identified by the presence of ground on the guard conductor corresponding to C130 for the link illustrated, whereas, 55 if the link is idle, battery is present on this conductor. Thus, immediately upon the operation of R340, ground is applied, at RA346 and RC347, to C130, thereby to mark the associated link as busy in the bank contacts of the rotary switch 60 670 and, with this switch standing in the position corresponding to this link, a circuit is completed for energizing the motor magnet M660. This circuit extends from ground at RC347 by way of RA346, C130, the switch wiper 671, C133, 65 RA606, and through the winding of M660 to battery. The magnet M660, upon being energized, steps its associated wipers 671 to 674, inclusive, one step so that the above-traced operating circuit is interrupted at the wiper 671 and the bank 70 contact terminating C130. If the link corresponding to the second contact of the contact set 675 is busy, ground is present on this contact and a new circuit is completed for energizing M660, thereby to cause this magnet to step the 75 enumerated wipers a second step. This action

is continued until such time as the wiper 671 encounters a contact in the associated set 675 corresponding to an idle finder-connector link. When this occurs, no further circuit is completed for energizing M660, and the operation of the rotary switch 670 is interrupted. With the switch standing in this new position, circuits are prepared for seizing the selected idle finder-connector link in the exact manner just described with reference to the link illustrated in Figs. 3 to 5, inclusive. 10

As was pointed out above, operation of R340, following the operation of the link to seize the calling line 11, is followed by operation of the cut-off relay R320 and the restoration of the line relay R310. The last-mentioned relay, upon restoring, interrupts at RA311, the operating circuit for R610, which latter relay, upon falling back, 15 interrupts, at RA613, the operating circuit for R605. The relay R605, upon restoring, opens the only remaining operating circuit for R620, causing 20 this relay to restore. Thus, the apparatus included in the allotter means illustrated in Fig. 6 is restored to normal and is prepared for further use.

As indicated previously, the seizure of any link 25 is accompanied by the operation of the relay corresponding to R420. Each of these relays, upon operating, functions to interrupt, at RA421 and RC423, a point in the operating circuit for R600. Hence, when all of the links are busy so 30 that all of the relays corresponding to and including R420 are energized, the operating circuit for R600 is completely open and this relay restores. As a consequence, it is impossible for a calling line to initiate the operation of any finder 35 switch in search thereof. A call initiated at a time when such a condition prevails will, therefore, not be rewarded with dial tone and cannot be extended until such time as one of the links is again idle. Obviously, when one of the links is 40 released following an all-links busy condition, the all-links busy relay R600 is again caused to operate. From the preceding description it will be apparent that when all of the links are busy the switch 670 continues to operate in search of an 45 idle link until R600 restores to cause the sequential restoration of R610 and R605. The last-mentioned relay upon restoring opens the operating circuit for M660 causing the switch 670 to discontinue its hunting operation. Thereafter, 50 and when R600, R610 and R605 are again caused to operate, the switch 670 is started in operation to find the idle link responsible for the re-operation of R600 and to assign this link to the calling line responsible for the operation of R610 55 and R605.

Operation of the power and supervisory apparatus

Before describing the operation of the connector portion of the link to select the called 60 line 16 in response to the transmission of impulses thereto from the calling substation A, and in order to render this portion of the description more clearly understandable, the operation of the power and supervisory apparatus, illustrated 65 in Fig. 7 and the lower portion of Fig. 6, will now be considered. As pointed out previously, this apparatus includes an inverter circuit, indicated as the ringing current source, for transforming the exchange battery voltage into an 70 alternating ringing voltage, a plurality of ringing current conductors, C154, C155, C156, C157 and C158, and a ringing interrupter comprising the rotary switch 710 and the associated control means for controlling the connection of the ring- 75

ing current conductors to the alternating voltage source. The arrangement of the enumerated elements is such that each of the ringing current conductors has impressed thereon the voltage of the source for coded intervals which are different for each of the various conductors. The power and supervisory apparatus also includes a timing device for generating spaced supervisory impulses which are utilized in the operation of any one of the links to lock out a faulty line until the fault is corrected, and are also utilized in the operation of the allotter means to cause different links successively to be assigned to a calling line in the event the assigned links fail to find a calling line. This apparatus further comprises means partially controlled by the ringing current interrupter for causing the connector portion of an operated link to search for an idle outgoing trunk line when a connection extending by way of such a line is desired by the calling subscriber. An additional feature of this apparatus pertains to the provision of circuit elements arranged to form a busy-tone current source and a dial-tone current source all in the manner described immediately hereinafter.

As pointed out above, the operation of the power and supervisory apparatus is initiated by the operation of R720 during the sequence of operations just described and immediately the link illustrated is taken for use. Upon operating, R720 completes a circuit for energizing R630, R645, R655, the upper winding of R700, and the upper windings of R705 and R707, respectively. This circuit extends from ground at RA721 to C136 where it divides, separate branches thereof extending through the designated windings of the various relays noted to battery. Through the operation of these relays, each of the various units referred to above is started in operation to perform the respective functions assigned thereto. Thus, the operation of the inverter illustrated in the lower left-hand corner of Fig. 6 is initiated upon the operation of the relays R630 and R645. The last-mentioned relay upon being energized attracts its weighted armature RA646 to prepare at RC649 a path for short-circuiting its own winding. This path is subsequently completed upon the operation of the slow-to-operate relay R630 and extends from battery at RA646 by way of RC649, RC634, RA632 and through the winding of RA645 back to battery. The relay R630, upon operating, also completes, at RA631, a circuit extending from ground on C136 for energizing the lower winding of R640, which latter relay operates after an interval, to open at RA642 and RC643, the path normally short-circuiting its upper winding and to prepare at RA641 a circuit for energizing the upper winding 682 of the transformer 680. With R645 deenergized, due to the short-circuited condition of its winding, the weighted armature RA646 is released and, upon its back stroke, engages RC647 to complete the above-noted circuit for energizing the transformer winding 682, this circuit extending from ground at the inductance coil 688 by way of the inductance coil 689, the winding 682, RA641, RC647 and RA646 to battery. The weighted armature RA646 upon its back stroke also interrupts the above-traced path short-circuiting the winding of R645, causing this winding to be energized in series with the resistor 636, whereby R645 again attracts RA646. On its second forward stroke the armature RA646 interrupts, at RC647, the above-traced circuit for energizing the transformer

winding 682 and completes, at its associated contacts RC648 and RC649, circuits for respectively energizing the lower winding 683 of the transformer 680 and the previously-traced path for short-circuiting the winding of R645. The energizing circuit for the winding 683 extends from ground at the inductance coil 688 by way of the inductance coil 689, the winding 683, RC644, RA642, RC648 and RA646 to battery. Obviously, with the winding of R645 short-circuited, the armature spring RA646 is again released and is again carried by its weighted end into engagement with RC647 to open the above-traced circuit for energizing the transformer winding 683 and to recomplete the above-traced circuit for 15 energizing the transformer winding 682. The armature noted, namely RA646, continues to vibrate alternately to complete the two above-traced circuits for energizing the two transformer windings 682 and 683. These two windings 20 are connected in opposition and, as a result, an alternating voltage is induced in the secondary winding 681, which is utilized for ringing purposes in the manner pointed out in detail hereinafter. Obviously, the frequency of this voltage is determined by the vibrating period of the armature spring RA646.

For the purpose of preventing arcing at the contacts controlled by the relay R648, a suppressor network is connected in shunt with the two series connected windings 682 and 683. This network comprises the condensers 685 and 687 and the resistors 684 and 686 connected in series, with the junction point between the two resistors connected to battery. The two inductance coils 688 and 689 are provided for the purpose of suppressing, in a conventional manner, transient currents which would interfere with the conversation ensuing over an established connection.

From the foregoing description it will be apparent that ringing voltage is generated continuously so long as R720 is maintained energized. This voltage is adapted to be impressed by a selected one of the five ringing current conductors C154, C155, C156, C157 and C158, comprising the cable 150, on one or both of the line conductors of a called line selected by any one of the links embodied in the office 18. The various paths for applying the voltage developed across the secondary windings of the transformer 680 to the five enumerated conductors are interrupted, through the operation of the rotary switch 710 and the control relays R707, R710 and R715, in a manner such that the ringing voltage as ultimately applied to the conductors of a called line is coded in a particular manner. More specifically, the arrangement is such that coded ringing voltage representing one long for each ringing cycle is applied to the ringing current conductor C158; coded ringing voltage representing two shorts for each ringing cycle is applied to C158; coded ringing voltage representing three shorts is applied during each ringing cycle to C154; coded ringing voltage representing four shorts is applied during each ringing cycle to C157; and coded ringing voltage representing one long and one short is applied during each ringing cycle to C155. The operation of the elements noted to interrupt the ringing voltage so that codes of the designated characteristics are applied to the respective enumerated ringing current conductors is initiated, as was pointed out above, upon the operation of R720 to complete a circuit for energizing R707. It will be noted that with the three relays R707, R710 and R715 deenergized, the windings of R710 and R715 are short-circuited over obvious paths. 75

When, however, R707 operates, it opens at RA708 a point in the path short-circuiting the winding of R710, permitting the last-mentioned relay to operate and interrupt at RA711 the path normally short-circuiting the winding of R715. The relay R715 in turn operates to complete, at RA716, an obvious path for short-circuiting the winding of R707, which latter relay now restores to re-complete at RA708 the path for short-circuiting the winding of R710. When R710 falls back, it in turn re-completes at RA711 the path for short-circuiting the winding R715, and the last-mentioned relay, upon restoring, opens, at RA716, a point in the path short-circuiting R707. Thus, the three relays noted, namely R707, R710 and R715 operate sequentially and continuously so long as R720 is held operated.

Each time R710 operates it not only functions to open the path for short-circuiting the winding of R715, but, in addition, completes a circuit for energizing M765 embodied in the rotary switch 770. This circuit extends from ground at RA721 by way of C136, RA712, C162 and through the winding of M765 to battery. Thus M765 is caused to drive its wipers 771 to 775, inclusive, at the rate of one step for each complete operating cycle of the three relays R707, R710 and R715.

At any given time when the two relays R710 and R715 are simultaneously in an energized condition, paths are prepared for extending the voltage developed across the secondary windings of the transformer 680 to each of the five enumerated ringing current conductors. Thus, with these two relays in their respective operated positions C138, which extends to the ungrounded terminal of the transformer winding 681, is connected by way of RC718, RA717, RA714 and C163 to the common conductor C161 which extends to selected ones of the various contacts in the three contact sets 791 to 793. By a proper selection and interconnection of the contacts to C161, ringing voltages, interrupted in accordance with the characteristics mentioned above, are applied to the respective ringing current conductors. For example, the conductor C158 is terminated at the wiper 773 associated with the contact set 793, and the common conductor C161 is connected to each of the second, third, eighth, ninth, fourteenth, fifteenth, twentieth and twenty-first contacts of this set. With the contacts of the set 793 thus connected, the operation of the switch is characterized by the application of voltage representing two shorts to the conductor C158.

Assuming the switch 770 is standing in the position shown, when the cyclic operation of R707, R710 and R715 is started, the above-traced circuit for M765 is completed upon the initial operation of R710. As a result, the wipers 771 to 775 are stepped to their respective first off-normal positions so that the wiper 773 engages its associated second contact. Shortly thereafter, R715 operates to complete a path for applying ringing voltage to C158, this path extending from C138 by way of RC718, RA717, RA714, C163, C161, the second contact of the set 793 and the switch wiper 773 to C158. Since the common conductor C161 is also connected to the respective second contacts of the sets 791 and 792, this voltage is also applied by way of the switch wipers 771 and 772, respectively, to the ringing current conductors C157 and C154. Shortly thereafter, and when R707 operates, R710 restores to interrupt, at RA714, a point in the above-traced path for applying the voltage to C161. Thereafter, and when R710 again operates to cause M765 to step its associated wipers a second step or into engage-

ment with their respective associated third contacts and R715 again operates, the paths noted are again completed, since the second and third contacts of each of the contact sets 791 to 793, inclusive, are connected together. When, however, the wipers of the switch 770 are stepped to their respective third off-normal positions, the above-traced path for applying ringing voltage to C158 is broken at the wiper 773, since C161 is not connected to the fourth, fifth, sixth and seventh contacts of this contact set. Hence only two short pulses of ringing voltage are applied to C158 during the period when the wiper 773 is traversing the first six active contacts. In the case of the contact set 792, however, it will be noted that the conductor C161 is connected to the second, third and fourth contacts so that three short pulses of ringing voltage are applied to C154 during movement of the switch wipers over the first six active points. In the case of the contact set 791, wherein C161 is connected to the second, third, fourth and fifth contacts, four short pulses are applied to the associated ringing current conductor C157. It is noted here that movement of the switch wipers 771 to 775, inclusive, over six points represents a complete ringing cycle. Thus, when the wiper 773 is stepped from its sixth to its seventh off-normal position, a new cycle is started, since the eighth and ninth contacts of the set 793 are connected to C161 in the manner previously described. In a similar manner, when the wipers 772 and 771 are stepped from their respective sixth to their respective seventh off-normal positions, a new ringing cycle is initiated. It will be apparent, therefore, that six complete operating cycles for the relays R707, R710 and R715 are required to produce a complete ringing cycle.

The method by which ringing voltage is applied to C156 for a relatively long time interval during each ringing cycle thereby to provide a ringing pulse representing one long, is slightly different from that just described for the production of pulses representing shorts. The production of long pulses is under the control of R780, having an operating circuit controlled by the wiper 774 in cooperation with its associated contacts. Thus, during the various ringing cycles, the wiper 774 completes circuits extending by way of the second, third, eighth, ninth, fourteenth, fifteenth, twentieth and twenty-first contacts of the set 794 and C160 for energizing the slow-to-release relay R780. This relay, upon operating, completes at RA784 and RC786, a path extending from C138 for applying to C156 the voltage developed across the secondary winding 681. Since the conductor C160 is multiplied between the various enumerated contacts of the contact set 794, it will be understood that R780 is caused to operate once during each ringing cycle and is held operated for the time interval required for the wiper 774 to traverse two of its associated contacts. Due to the prolonged portion of each ringing cycle when R780 is energized, a voltage pulse is applied to C156 during each ringing cycle which is of sufficient length to distinguish the same from the short pulses applied to C154, C157 and C158.

With respect to the coded ringing voltage applied to C156 and comprising one long impulse and one short impulse for each ringing cycle, it will be noted that the long impulse is attained through the operation of R780 directly to apply at RA781 and RC783 the voltage on C138 to the ringing current conductor C155. This long pulse is held until the wiper 774 is stepped from engage-

ment with its associated third contact and into engagement with its associated fourth contact, at which time the operating circuit for R780 is opened and an alternative path is prepared, at 5 the switch wiper 772 and its associated fourth contact, for applying a short pulse of voltage to C155. This path is completed upon the operation of R715 and extends from C138 by way of RC118, RA717, RA714, C163, C161, the fourth contact of 10 the set 792, the switch wiper 772, RC182 and RA781 to C155. It is believed clear without further discussion that the production of this particular code occurs once during each ringing cycle.

15 Ground potential is, at all times, applied to each of the five enumerated ringing current conductors for the purpose of energizing the ring cut-off relays of the links in the manner described hereinafter. Thus, those contacts of each 20 of the contact sets 791 to 793, inclusive, excepting the first contacts of each set, which are not active in the paths for applying voltage to the ringing current conductors, are grounded so that ground is directly applied to the respective conductors 25 C158, C154 and C157 when the respective associated wipers are stepped into engagement therewith. For the same purpose, the armatures RA714 and RA717, embodied respectively in the relays R710 and R715, are arranged to be connected 30 to ground, when restored, so that ground may be applied to the active contacts of the contact sets 791 to 793, inclusive, for a portion of each operating cycle of the relays R707, R710 and R715. In a similar manner, the armature RA784 embodied 35 in the relay R780 is arranged to be connected to ground at RC185 during those intervals when R780 is restored, so that ground is extended by way of the elements noted to C156. Direct current ground potential is also applied to each 40 of the five enumerated conductors during the periods when alternating ringing current voltage is applied thereto, it being extended, during such periods, from the grounded terminal of the transformer winding 681 and by way of the conductor 45 C138 to each of these conductors.

Referring now more particularly to the operation of the relay R700, it is pointed out that this relay functions as a source of busy-tone current. Thus, when the upper winding of this relay is 50 energized from ground at RA721, upon operation of R720, it operates to complete at RA701 a circuit also extending from ground at RA721 for energizing its lower winding. The two windings of R700 are connected in opposition so that when 55 the lower winding thereof is energized, the relay immediately restores to open at RA701 the circuit for energizing its lower winding. Immediately this circuit is opened, the upper winding is effective to cause the relay to reoperate. Hence, it 60 will be seen that this relay operates in the manner of a buzzer. Each time R700 operates, it short-circuits, at RA701, the circuit comprising the resistor 703 connected in series with the exchange battery. Due to the repeated short-circuiting 65 of these two series connected elements, an alternating voltage is developed across the resistor 703, which is extended by way of the filter choke 704 and the armature RA713 to the busy-tone conductor C147. From the above description 70 it will be apparent that the cyclic operation of R715 causes an interrupted busy-tone voltage to be applied to the busy-tone conductor noted.

The relay R705 operates in a manner similar to that just discussed with reference to R700 to 75 develop across the resistor 702 an alternating

voltage which comprises a dial tone current source. Thus, when R720 operates, it completes, at RA721, an obvious circuit for energizing the upper winding of R705. This latter relay immediately operates to complete, at RA706 and RA707, a circuit for energizing its lower winding. The two windings of R705, like those of R700, are connected in opposition so that, when the above-noted circuit is completed, this relay restores to open the operating circuit for its lower winding. 10 Immediately this occurs, the upper winding is again effective and the relay reoperates. It will be seen, therefore, that R705 functions in the manner of a buzzer so long as R720 is held operated. Each time R705 operates, it short-circuits, 15 at RA706 and RA707, the series circuit comprising the exchange battery and the resistor 702. Hence, through the repeated operation of R705, an alternating voltage is developed across the resistor 702 which is impressed through the filter 20 choke 704 on the dial tone current conductor C151. This current is generated so long as the relay R720 is maintained in its operated position.

As noted previously, the power and supervisory apparatus includes means for controlling the connector portion of any seized link in its operation to select an idle trunk outgoing from the exchange 10 and following the dialing of the number identifying the group of trunk lines. Specifically, this means comprises the two relays R650 25 and R655, which function to apply ground pulses to the several supervisory conductors C138, C139', etc. extending, respectively, to the control apparatus individually embodied in the several links provided in the exchange 10. The operation of 30 these two relays to perform the function noted is initiated when R720 operates to complete, at RA721, a circuit extending by way of C138 for energizing the slow-to-release, slow-to-operate relay R650. This relay, upon being energized, 35 operates after an interval to short-circuit at RA656 its operating winding and to complete at RA657 an obvious circuit for energizing R650. The last-mentioned relay now operates to complete, at its armatures RA651 and RA652, etc., 40 paths for applying ground to the supervisory conductors C138, C139', etc. After the winding of R655 has been short-circuited for an interval, this relay restores, so that its winding is again energized to cause its reoperation. During the 45 period of restoration, however, R650 is caused to restore, so that ground is removed from the various supervisory conductors noted. It will be appreciated that the repeated operation and restoration of R655 to cause the repeated operation 50 and restoration of R650 continues so long as ground is maintained on C138, or, so long as R720 is held operated.

The timing device, referred to briefly above, 55 comprises more particularly the plurality of interrelated relays R724, R730, R735 and R740, which relays are controlled by means including the rotary switch 770. This device functions to apply ground pulses to the supervisory leads C137, C148 and C135 at spaced time intervals, which 60 ground pulses are utilized to cause the allotter means illustrated in Fig. 6 to assign a new link in search of a calling line in the event a first assigned link fails to find the calling line, and further to cause a defective line to be locked out 65 of service. The particular portion of the switch 770 which enters into the operation of the timing device comprises the contacts of the set 794 and the associated wiper 774. Thus when R720 operates to initiate the operation of the switch 770 70 75

and when this switch steps its wipers to their respective third off-normal positions, a circuit is completed at the switch wiper 714 for energizing R735, this circuit extending by way of the wiper 5 noted, the fourth contact of the set 794, C166, RC746, RA744, and through the winding of R735 to battery. The relay R735, upon operating, completes, at RA736, a path for applying ground to the supervisory conductor or time pulse lead C137. 10 This path extends from ground on C122, RA728, RA741, RC742 and RA736 to C137. The completion of this path in the manner noted represents the first ground pulse applied to the supervisory conductor C137. The relay R735, upon operating, 15 also prepares, at RA738, a locking circuit for itself, but this locking circuit is not completed at this time due to the deenergized condition of R740. When the wipers of the switch 710 are stepped from their respective third off-normal 20 positions, the above-traced operating circuit for R735 is broken at the switch wiper 714, causing this relay to restore.

Thereafter, and when the switch wipers are rotated into engagement with their respective associated twenty-fourth contacts, a circuit is completed for energizing R740, this circuit extending from ground on the switch wiper 714 by way of the twenty-fourth contact of the set 794, C168 and through the lower winding of R740 to battery. The relay R740 now operates to complete 30 at RA747 a locking circuit for itself, which circuit includes the upper winding of R740 and extends from ground on C122. At RA741, the relay R740 opens a point in the above-traced path for applying ground to C137 and prepares a point in the holding circuit for R735. At RA744 and RC746, the relay R740 opens a point in the above-traced operating circuit for R735 and prepares an alternative operating circuit therefor.

40 During continued operation of the switch 710 the wiper 714 is brought into engagement with the twenty-third contact of the contact set 794 so that the last-mentioned operating circuit for R735 is completed, this circuit extending from ground on the wiper 714 by way of C167, RC745, RA744 and through the winding of R735 to battery. Upon operating the second time, R735 completes at RA738 a holding circuit for itself, which circuit extends from ground on C122 by way of 45 RA728, RA741, RC743, RA738 and through the winding of R735 to battery. At RA736, the relay R735 prepares a point in the above-traced path for applying ground to C137, this path now being open at RA741 and RC742 of the operated relay R740. At RA731, the relay R735 opens a point 50 in the holding circuit traced hereinafter for R724 and at RA739 it prepares a point in the operating circuit for R730.

55 After a time interval during which the switch 60 710 continues to operate, the switch wiper 714 is rotated into engagement with the twenty-second contact of the contact set 794, thereby to complete a circuit extending by way of C165 and RA739 for energizing R730. The last-mentioned 65 relay, upon operating, completes, at RA731, a holding circuit for itself and prepares, at RA732, a circuit for energizing R724. The holding circuit noted, namely that for R730, extends from ground on C122 by way of RA728, RA731 and through the winding of R730 to battery.

70 After a still further time interval during which the switch 710 continues to operate, the wiper 714 is driven into engagement with the nineteenth contact of the set 794, thereby to complete 75 the above-noted operating circuit for R724, which

circuit extends from ground on the wiper 714 by way of C164, RA732, and through the winding of R724 to battery. The relay R724, upon operating, opens at RA728 a point in each of the above-traced holding circuits for the relays R730, R735 5 and R740, causing these relays to restore. At RA729, the relay R724 prepares a holding circuit for itself, which circuit is completed at RA731 before the slow-to-release relay R730 falls back to restore its armature RA732. In this connection it is pointed out that the switch 714 stands in engagement with its associated nineteenth contact for a time interval sufficient to permit each of the relays R730, R735, and R740 to restore, and the relay R724 to be energized. 10

15 It will be noted that with R724 deenergized, ground is normally applied from RA725 by way of RC726 to the supervisory conductor C148. When, however, R724 operates, ground is removed from this conductor and is applied to the 20 supervisory conductor C135 at RC727. The operation of this armature to remove ground from C148 and to apply ground to C135 is responsible for certain of the supervisory operations referred to more specifically in a following portion 25 of the specification.

The relay R724 is held operated until such time as the switch wiper 714 is again driven into engagement with the fourth contact of the set 794, at which time the previously traced operating circuit for R735 is completed. The relay RA735, upon operating a third time, opens at RA731 the above-traced holding circuit for RA724, causing this relay immediately to restore. At RA736 the relay RA735 prepares a point in the path described above for applying ground to the supervisory conductor C137, this path being subsequently completed when R724 restores its armature RA728. Thus, a second ground pulse is applied to C137 a definite time interval following the 30 application of the first ground pulse to this conductor. In view of the preceding description, it will be understood that the cyclic mode of operation of the four relays R724, R730, R735 and R740 under the control of the switch 710 is continued 35 so long as R720 is held operated to maintain the switch 710 in operation.

40 As noted above, rotation of the switch wipers embodied in the switch 710 over twenty-five points corresponds to the completion of four ringing cycles. In order that this switch shall be conditioned to start a ringing cycle irrespective of when the power and supervisory apparatus is released, there is provided an alternative circuit for maintaining R720 energized independently of the condition of R420 embodied in the control apparatus of the link illustrated, or a corresponding relay of another link. This circuit extends from ground at the switch wiper 715 by way of C159, RA722 and through the winding of R720 to battery. As 45 shown, the conductor C159 is connected to each of the contacts of the contact set 795 corresponding to the active points of each of the other contact sets. Hence, if R420 is caused to restore to remove ground from the start conductor C122 50 while the wipers of the switch 710 are standing in their respective fourth off-normal positions, for example, the relay R720 is held energized over the circuit just described until the switch wipers are rotated to their respective sixth off-normal 55 positions, at which time this alternative circuit for R720 is interrupted, causing an interruption in the cyclic operation of the control relays R701, R710 and R715. There results the stopping of the switch 710 with the wipers thereof standing in 60 65 70 75

their respective sixth off-normal positions in preparation to start the second ringing cycle. It is noted that if the switch 770 is thereafter started in operation from this position, a slightly longer time interval will necessarily be required for the application of the two ground pulses to the supervisory conductor C181. Thus, the relay R735 is not effective to apply ground to this conductor until R740, R730 and R724 have first been caused to operate and have thereafter restored. It will be appreciated, therefore, that only when the wipers are started from the position shown in the drawings is the first ground pulse applied to C181 immediately the operation of the power and supervisory apparatus is initiated.

In order to make the time interval separating the end of the fourth ringing cycle, as determined by the operation of the switch 770, from the beginning of the first ringing cycle during continuous operation of this switch, there is provided an alternative circuit for energizing M765 when the switch is operated to its twenty-fourth off-normal position. This circuit, which is completed immediately following the completion of the fourth ringing cycle, extends from ground on the switch wiper 775 by way of the twenty-fifth contact of the set 795, the self-interrupting contacts associated with MA766 and the winding of M765 to battery. Hence, the switch is stepped immediately to the starting position for the first ringing cycle immediately the fourth ringing cycle is concluded.

As pointed out previously, apparatus is provided for transmitting alarm signals to an attendant, which signals are of a different character, depending upon the condition of the power and supervisory apparatus as illustrated in Figs. 6 and 7. Thus, current from the exchange battery is conducted through fuses 757, 757', etc. to the various control relays and operating magnets included in the several links, the allotter means and the power and supervisory equipment. In the event any one of these fuses is disrupted, a circuit is completed, by way of the conductor 762, the disrupted link and the conductor 762', for energizing the upper winding of R750. Similarly, if for some reason the battery charging circuit becomes defective, one or both of the two relays R755 and R760 are caused to restore, thereby to complete an obvious circuit for energizing the lower winding of R750. The relay R750 operates when either of its windings are energized, and, upon operating, connects the alarm conductor C152 to the ringing current conductor C155 at RA751 and RC753. The ringing voltage impressed on C155 is of a particular characteristic indicating a fault in the power and supervisory apparatus. Obviously, with R750 energized this voltage is impressed on the alarm conductor C152 which extends to each of the links provided in the exchange 10.

Normally, and with the power and supervisory apparatus in proper working order, the alarm conductor noted is connected by way of RA751 and RC752 to the ringing current conductor C156. This ringing current conductor has impressed thereon, in the manner described previously, ringing voltage of a particular characteristic. If, therefore, an operator or attendant, upon checking the apparatus in the manner pointed out hereinafter, receives a signal produced by this characteristic voltage, he is informed that the apparatus is in proper working order. Obviously, if the power and supervisory apparatus is for some reason disabled or fails to function, no voltage is impressed on C156, and hence no tone will

be received upon checking the apparatus. The absence of tone or the receipt of a tone produced by the voltage on C155 indicates that the power and supervisory apparatus is out of order.

Operation of the connector switch to select the called subscriber's line 5

Before continuing with the description pertaining to the operation of the connector portion of the link to select the desired called line, 10 it is again pointed out that the subscribers' lines terminating at the bank contacts of the connector switch are divided into two groups. The first group includes the lines numbered from 11 to 10, inclusive, and the second group comprises 15 the line numbered from 31 to 39, inclusive. In the present assumed case, the called substation B is connected to line No. 16 terminating at the bank contacts of the switch 550. Hence, the first digit dialed at the calling subscriber's substation will necessarily comprise a single impulse. At the beginning of this impulse, the relay R370, 20 which is now held operated over the loop circuit extending to the substation A, restores, to interrupt, at RA371, the above-traced circuit for R410. 25 The last-mentioned relay, in turn, restores to open, at RA411, a point in its own locking circuit and to interrupt, at RA412 and RC413, the operating circuit for R403. The relay R410, upon restoring, further completes, at RA412 and RC414, 30 a circuit for energizing R480, this circuit extending from ground at RA412 by way of RC414, RA424, C189, RA493', RC495', and through the winding of R480 to battery. The relay R480, 35 upon operating, completes, at RA481, a circuit extending by way of RC482 for energizing the lower winding of R460, which latter relay operates to prepare, at RA462, a circuit, traced hereinafter, for energizing R490.

The relay R480, upon operating, further completes, at RA484, a circuit for energizing the motor magnet M540 embodied in the rotary switch 550. This circuit extends from ground at RA412 by way of RC414, RA424, C189, RA493', RC495', RA484, RA498, RC499', C190 and 45 through the winding of M540 to battery. In response to its energization over the above-traced circuit, M540 is prepared to cause the wipers 581 to 585, inclusive, to be stepped from their respective home positions to their respective first off-normal positions. 50

At the end of the first impulse, when R370 again operates, the above-traced circuit for energizing R410 is recompleted at RA371, and the operating circuit for R403 is recompleted at RA372 and RC373. The relay R410, upon re-operating, interrupts, at RA412, the above-traced circuits for R480 and M540 and recompletes, at RA411, its own holding circuit. This relay further completes, at RA412 and RC413, 60 the holding circuit for R403. When M540 is de-energized, it steps the associated wipers 581 to 585, inclusive, one step or to their respective first off-normal positions. It will be understood that during each impulse following the first impulse of the first digit, the above-described sequence of operations is repeated, and, further, that R403 and R480, due to their slow-to-release characteristics, remain operated during impulsive. In the present case, wherein the first digit 70 dialed comprises a single impulse, the switch 550 is caused to take only one step. Shortly following the conclusion of the digit, R480 restores, to interrupt, at RA481, the above-noted circuit for energizing the lower winding of R460. The 75

last-mentioned relay now restores to complete, at RA461, a circuit for energizing R450, this circuit extending from ground at RA421 by way of RC422, C188, the switch wiper 584, C180, RA461, 5 and through the winding of R450 to battery. At RA455, the relay R450, upon operating, prepares a circuit traced hereinafter, for energizing the busy relay R470 and, at RA451, it opens a point in the circuit for conducting dial tone current 10 from the source R705 to the receiver at the calling substation A. At RA452, the relay R450 completes a circuit for short-circuiting the upper winding of R460, thereby to render the last-mentioned relay slightly slow-to-operate. At RA453, 15 the relay R450 completes a holding circuit for itself, this circuit extending from ground at RA421 by way of RC422, C188, C179, RA453 and through the winding of R450 to battery. With the link in this condition, the control apparatus 20 in the connector portion thereof is conditioned to respond to the second series of impulses transmitted thereto.

From the foregoing description, it will be understood that R370 and R410 follow the impulses 25 of the second digit in the exact manner described above with reference to the first digit dialed at the calling substation. It will further be understood that the relays R480 and R460 are caused to operate and stay operated continuously during 30 the transmission of the second series of impulses. Since the called line is the sixth line in the first group, the second digit dialed at the calling substation must necessarily comprise six impulses and, during each impulse, M540 is caused to operate in the manner described above to step its 35 wipers one step. Hence, at the conclusion of the second digit, the wipers 581 to 585, inclusive, stand in engagement with the contacts at which the conductors of the called line 16 are terminated. The operations which occur following the dialing 40 of the second digit differ depending upon whether the called line is idle or busy at the time it is selected.

Before describing these operations, however, 45 attention is directed to the mode of operation of the connector switch to select a called line in the second group of lines. In this case, the first digit dialed at the calling substation will comprise three or more impulses instead of one. Assuming three impulses are dialed, the switch 550 steps its wipers 581 to 585, inclusive, to their respective third off-normal positions. At the conclusion of the first digit, therefore, no circuit is completed for energizing R450 following the restoration of R460. A circuit is completed, however, for energizing M540 by way of the self-interrupting contacts associated with MA542, this 50 circuit extending from ground at RA421 by way of RC422, C188, the switch wiper 584, the fourth contact of the set 554, C194, RA457, C121, RA465, RA497, RC499, C196, the self-interrupting contacts associated with MA542, and the winding of M540 to battery. This circuit is alternatively interrupted and completed, by virtue 55 of the multiple connection between the fourth to thirteenth contacts of the contact set 554, until such time as the switch wipers are stepped to a position wherein the wiper 584 stands in engagement with the associated thirteenth contact of the contact set 554. With the wiper noted 60 in this position, the above-traced operating circuit for M540 is interrupted so that further operation of the switch 550 is prevented, and the above-traced circuit for energizing R450 is completed. Since the third to twelfth contacts of

the contact set 554 are multiplied together it will be apparent that any first digit comprising more than two impulses and less than eleven impulses will cause the connector switch to operate to select the second group of subscribers' lines. 5 For example, a first digit of 6 will cause the wipers of the switch 550 to be operated to their respective sixth off-normal positions so that at the conclusion of the digit the above-noted circuit is completed for energizing M540 by way 10 of the self-interrupting contacts associated with MA542.

The respective thirteenth contacts of the contact sets 551 to 553, inclusive, are dead, the conductors of the last subscriber's line of the first 15 group being respectively terminated at the twelfth contacts of these three contact sets and the conductors of the first line of the second group being terminated at the respective fourteenth contacts of the contact sets 551, 552 and 553. Hence, 20 with the switch 550 in its twelfth off-normal position it is conditioned to respond to the impulses of the second digit dialed at the calling substation. The operations which occur immediately following the dialing of the first digit of 25 three or more impulses and during the dialing of the second digit will readily be understood in view of the preceding description.

Operation of the connector switch when the 30 called line is busy

Continuing now with the operations which occur following the selection of the called line 16, and assuming that this line is busy so that ground potential is present on the control conductor 35 C593, a circuit is completed immediately the line is selected for energizing the busy relay R470, this circuit extending from ground on the control conductor C593 by way of the switch wiper 583, C186, RC496, RA494, RA455 and the winding 40 of R470 to battery. The relay R470, upon operating, prepares, at RA473 and RC475, a holding circuit for itself, and at RA471 opens a point in the circuit traced hereinafter for energizing the ringing relay R530. At RA476, the relay 45 R470 opens a point in the circuit, traced hereinafter, for energizing the switching relay R350 and, at RA472, it connects the busy-tone current source to the partially completed talking circuit extending to the calling substation A, 50 thereby to indicate to the calling party that the called line is busy. The path traversed by this current extends from one side of the busy-tone source at RA713 by way of C147, RA433, C182, RA504, C181, RA472, one side of the loop extending to the calling substation, through the receiver at the calling substation and back over the other side of the subscriber's loop to the opposite side of the busy-tone source at the lower 55 terminal of the upper winding of R370. 60

Shortly following the end of the second digit, R480 restores due to the interruption of its operating circuit at the now-operated armature RA412 of the pulsing relay R410. When R480 restores, it opens, at RA481, the operating circuit for R460 and completes, at RA481 and RC483, a circuit for energizing R490. The last-mentioned circuit extends from ground at RA481 by way of RC483, RA462, RA454, RA492, and through the winding of R490 to battery. The 70 last-mentioned relay, upon operating, completes, at RA497, a holding circuit for itself, which circuit extends from ground at RA421 by way of RC422, C188, RA497, and through the winding of R490 to battery. At RA494 and RC495 the re- 75

lay 490, upon operating, completes the above-noted holding circuit for the busy relay R470, this circuit extending from ground at RA421 by way of RC422, C188, C185, RA473, RC475, RC495, 5 RA494, RA455, and through the winding of R470 to battery. At RA492, the relay R490 opens a point in its operating circuit and, at RA498, it prepares a pulsing circuit to the operating magnet M565 of the ringing code-selecting switch 10 560.

If the calling subscriber fails to hear busy tone or to heed the busy-tone signal and continues to dial the third digit of the number identifying the called subscriber's substation, the impulses of this digit cause the relays R370, R410, R480, and R460 to operate as before described. Hence, during each impulse of this third digit, a circuit is completed for energizing M565 embodied in the code-selecting switch 560. This 15 circuit extends from ground at RA412 by way of RC414, RA424, C189, RA493', RC495', RA484, RA498, RC499, RA496', RC491, C197, and through the winding of M565 to battery. As a consequence of the impulses transmitted to the 20 magnet M565, the wipers 563 and 564 of the switch 560 are operated to a position corresponding to the coded ring identifying the particular called subscriber's substation connected to the called line 16. When these wipers are stepped 25 to their respective first off-normal positions, the off-normal springs 571 and 573 are closed to prepare circuits for energizing, respectively, the relay R490' and the release magnet M566 embodied in the rotary switch 560.

30 35 Shortly following the end of the third digit, when the two relays R480 and R460 restore, in the order named, the above-noted circuit for energizing R490' is completed, this circuit extending from ground at RA481 by way of C198, 40 the off-normal springs 571, C178, and through the winding of R490' to battery. When R490' operates, it interrupts, at RA496' and RA493', points in the above-traced circuit for energizing M565 in accordance with the impulses comprising 45 the third digit. It is noted that, with R470 held operated, the circuit for energizing the ringing relay R530 is maintained open and thus no ringing current is applied to the line conductors of the selected called line. The link 50 remains in the condition which prevails following the operation of R490' until such time as its release is initiated, in the manner pointed out in detail hereinafter, at the calling substation A.

55 *Operation of the connector switch when the called line is idle*

If, instead of being busy, the called line 16 is idle at the time it is selected by the connector 60 portion of the link, the busy relay R470 is not energized. Thus, if the called line is idle, this condition is indicated by the presence of battery potential on the control conductor C593 and consequently, the above-traced energizing circuit for 65 R470 is not completed when the wipers of the switch 550 are operated to the off-normal position corresponding to the called line. When, therefore, R480 restores shortly following the end of the second digit to interrupt the operating circuit for R460, a circuit is momentarily completed for energizing R490, this circuit extending from ground at RA481 by way of RC483, 70 RA462, RA454, RA492, and through the winding of R490 to battery. The last-mentioned relay, 75 upon operating, completes, at RA491, the above-

traced holding circuit for itself and interrupts, at RA492, the circuit, just traced, over which it was initially energized. At RA493, the relay R490 completes a circuit for energizing the cut-off relay associated with the called line 16 and corresponding to R320 for the calling line. This circuit extends from ground at RA421, by way of RA422, C188, C185, RA473, RC474, RA498, C186, the switch wiper 483, C593, and through the winding of the cut-off relay noted to battery. At RA498 and RC498 the relay R490 prepares the above-traced impulsive circuit for energizing M565 embodied in the code-selector switch 560 in accordance with the impulses of the third digit dialed at the calling subscriber's 16 substation.

10 It will be understood that the application of ground to the control conductor C593, thereby to energize the cut-off relay associated with the called line 16, marks the called line as busy in 20 the bank contacts of the connector switches embodied in the other finder-connector links to which the called line extends. From a consideration of the line circuit associated with the calling line 11, it will be seen that when the 25 cut-off relay associated with the called line operates, it disconnects the windings of the associated line relay from the line conductors C591 and C592 of the called line, thereby to clear this line for the transmission of voice frequency and ringing currents.

30 When the third digit is dialed at the calling subscriber's substation, the magnet M565 is energized in accordance with the impulses making up this digit so that, at the conclusion of the 35 digit, the wipers of the switch 560 stand in engagement with the contacts of the respective associated contact sets 561 and 562 which correspond to the coded ring identifying the particular desired substation connected with the 40 called line. Since the use of line-to-ground ringing on each side of the line circuit embodying the line conductors of the called line is contemplated, the switch 560 further operates to select, in accordance with the impulses comprising the 45 third digit, the side of the called line over which ringing current is to be transmitted. Thus, if it be assumed that the ringing or signal device at the called substation B is connected between the negative line conductors C591 and ground 50 and that the particular ring identifying this substation is one long, the third digit will comprise two impulses so that, at the conclusion thereof, the switch wipers 563 and 564 stand in engagement with their respective associated second contacts embodied, respectively, in the contact sets 561 and 562. It will be understood that when the wipers of the switch 560 are operated to their respective first off-normal positions, the off-normal springs 571 and 573 are closed in the 55 same manner as was described above.

At the conclusion of the third digit dialed at the calling subscriber's substation when R480 again restores, the above-traced operating circuit for R490' is completed. This relay, upon operating, opens the above-traced impulsive circuit for M565 and prepares a circuit for energizing the release magnet M566. At RA491', the relay R490 prepares a circuit for energizing the ringing relay R530, this circuit being subsequently 60 completed when the wiper 775 of the switch 770 is operated to a position corresponding to the beginning of a ringing cycle. Thus, if this wiper is in engagement with its associated third contact at the time R490' operates, the operating 75

circuit for R530 is not completed until the wiper noted has been stepped four steps or into engagement with its associated seventh contact, which contact corresponds to the beginning of the second ringing cycle, as described above. When, however, the wiper 715 is operated into engagement with any one of its first, seventh, thirteenth, or nineteenth associated contacts, the above-noted circuit for R530 is completed, this circuit extending from ground at the wiper noted by way of any one of the four contacts noted, C146, C102, RA351, C103, RA471, RA491, C176, RA534, and through the winding of R530 to battery. This relay operates, after a short interval, to complete at RA533 and RA534, a holding circuit for itself, this circuit extending from ground at RA421 by way of RC422, C188, C179, RA533, RA534, and through the winding of R530 to battery. The relay R530, upon operating, completes a circuit for transmitting ringing current to the signal device at the called substation B by way of the negative line conductor C591. Specifically, this circuit extends from the upper terminal of the transformer winding 681 by way of C138, RC786, RA784, C156, the two contacts corresponding to the second off-normal position of the switch wiper 563, the switch wiper 563, C205, RA531, RC522, RA521, C105, the switch wiper 581, C591 and through the signal device bridged between C591 and ground at the called substation. Since the lower terminal of the transformer winding 681 is grounded, a complete circuit is thus established for energizing the signal device at the called substation for the period of time corresponding to one long during each ringing cycle of the apparatus illustrated in Fig. 7. With the ringing relay R530 operated, a portion of the ringing current is by-passed by way of the loop extending to the calling subscriber's substation to generate a ring-back tone in the receiver located at the calling substation. The path of this current extends from one side of the ringing current source as extended by the switch 560 to C205 by way of RA531, RC522, RA521, RA532, the condenser 591, C104, the condenser 388, RC353, RA352, RA341, the switch wiper 381, C392, the receiver at the calling substation A, C393, the switch wiper 382, RA342, RA355, RC356, and through the lower winding of R370 to the grounded side of the transformer winding 681. With ringing current of the proper code being transmitted to the signal device at the called substation B and ring-back tone current being transmitted to the calling subscriber's substation, the called subscriber is informed that a call awaits his attention and the calling subscriber is informed that the desired called substation is being signalled.

Before describing the operations which occur when the called party answers, and in order to complete the description pertaining to the operation of the ringing code-selector switch 560, it will be assumed that the signal device at the called substation B is bridged between the positive line conductor C592 and ground and that the coded ring corresponding to the called substation is three shorts rather than one long. In this case the third digit dialed at the calling substation will necessarily comprise five impulses instead of two, so that, at the conclusion thereof, the switch wipers 563 and 564 stand in their respective fifth off-normal positions. Shortly following the conclusion of the third digit, R490' is energized to prepare the operating circuit for the ringing relay R530, which latter relay is ener-

gized in the exact manner described above, at the beginning of a ringing cycle as determined by the operation of the rotary switch 710. This relay, upon operating, completes the circuit for extending ringing current by way of C592 to the signal device at the called substation, completes its own locking circuit as described above, and completes the circuit for extending ring-back tone current to the receiver at the called subscriber's substation. In this case, however, the circuit for the ringing current extends from the upper terminal of the transformer winding 681 by way of C138, RC718, RA717, RA714, C153, the switch wiper 722, C154, the respective fifth contacts associated with the switch wiper 563, C204, RA536, RC527, RA525, C109, the switch wiper 582, C592, and through the grounded signal device connected to C592 to the opposite terminal of the winding 681. From the immediately preceding description, it will be appreciated that the one of the positive or negative line conductors of a selected line to which the ringing current is applied is determined by the odd or even number of the impulses comprising the third digit dialed at the calling subscriber's substation. Thus, if this digit comprises a single impulse, coded ringing current comprising one long impulse for each ringing cycle is transmitted by way of the positive line conductor C592 or the positive line conductor of another selected line to a signal device bridged between this line conductor and ground. If, as was described above, the third digit comprises two impulses, this same coded ringing current is conducted by way of a negative line conductor, corresponding to or comprising C591, to the signal device or devices bridged between this line conductor and ground. Similarly, if the selected coded ring of a desired substation is two shorts and the substation is connected between a positive line conductor and ground, the third digit dialed will necessarily comprise three impulses so that, at the conclusion thereof, the wipers 563 and 564 stand in their respective third off-normal positions, or, if the coded ring of a desired substation is two shorts and the signal device thereat is bridged between the negative line conductor and ground, the third digit dialed at the calling substation will necessarily comprise four impulses. The operation of the code selecting switch 560, to select coded ringing current of three shorts, four shorts, or one long and one short, and selectively to apply this current to either the positive or negative line conductor of a selected line, is accomplished in a similar manner.

With the code selector switch 560 standing in any selected off-normal position, a circuit is prepared for energizing the ring cut-off relay R520 when the called substation is answered. Thus, to continue with the description set forth above wherein the signal device of the called substation is connected between the positive line conductor C592 and ground and the coded ring identifying this substation consists of one long ringing current pulse for each ringing current cycle, with the switch wipers 563 and 564 standing in their respective second off-normal positions, a circuit is prepared for energizing the ring cut-off relay. This circuit, which is completed when the call is answered at the called substation B, extends, from ground at RC785 by way of RA784, C156, the switch wiper 563, C205, RA531, RC522, RA521, C105, the switch wiper 581, C591, the bridge across C591 and C592 at the called substation, C592, the 75

- switch wiper 582, C109, RA525, RC527, RA536, C204, the switch wiper 564, C206 and through the lower winding of R520 to battery. From the preceding description, it will be remembered that, direct current ground potential is, at all times, present on each of the ringing current conductors C154 to C158, inclusive, so that, irrespective of the one of these conductors which is selected by the switch 560, a circuit is completed for energizing the ring cut-off relay R520 when the called substation is answered. It will be noted, however, that the path of the current through the winding of R520 is different, depending upon the number of impulses making up the third digit. The circuit just described is that which is completed when the number of impulses of the third digit is even, this circuit being the same for any even number of impulses with the exception that ground may be extended by way of any selected one of the five ringing current conductors C154 to C158, inclusive, to the switch wiper 563. In the event the number of impulses making up the third digit is odd, the circuit over which the ring cut-off relay is energized extends from ground on a selected one of the five ringing current conductors by way of the switch wiper 563, C204, RA536, RC527, RA525, C109, the switch wiper 582, C592, the bridge across C592 and C591 at the called substation, C591, the switch wiper 581, C105, RA521, RC522, RA531, C205, the switch wiper 564, C206 and through the lower winding of R520 to battery. When the lower winding of R520 is energized over either of the two above-traced circuits, it attracts RA524, after an interval, to complete a circuit for energizing its upper and lower windings in series, this circuit extending from ground at RA421 by way of RC422, C188, C179, RA524, and through the two windings of R520 in series. The relay R520 now fully operates and, at its armatures RA521 and RA525 and their respective associated contacts RC522 and RC527, interrupts points in the above-traced circuits for applying ringing current to the selected line conductor extending to the called substation, opens a point in the path for conducting ring-back tone current to the calling subscriber's receiver, and opens two points in the above-traced alternative circuits over which the lower winding of R520 is initially energized. At these same armatures and their respective associated contacts RC523 and RC526, the cut-off relay R520 completes a talking loop between the calling and called substations. The completion of the talking loop results in the energization of R400 over a circuit extending from ground at the upper terminal of the lower winding of this relay by way of C108, RC526, RA525, C109, the switch wiper 582, C592, the bridge across C591 and C592 at the called substation, C591, the switch wiper 581, C105, RA521, RC523, C104 and through the upper winding of R400 to battery. The relay R400 now operates to complete, at RA401, a circuit extending by way of C107 for energizing R360, and the last-mentioned relay, in turn, operates to reverse, at RA361, RA362, RA363 and RA364, the battery potential applied to the line conductors extending to the calling substation. At RA365, the relay R360 opens a point in the circuit, traced hereinafter, for energizing R440. With the apparatus in this condition, the calling and called parties may converse as desired, talking battery being supplied to the loop extending to the calling subscriber's substation from the windings of R370 and talking battery being supplied to the

loop extending to the called subscriber's substation from the windings of R400.

Release of the finder connector link

As pointed out in the introductory portion of the specification, the release of a connection established in the above-described manner is entirely under the control of the calling party. Thus, when the called party B hangs up first, the only operations which immediately occur are the restoration of R400, followed by the restoration of R360, which latter relay, upon falling back, reverses battery as applied to the loop extending to the calling subscriber's substation and reestablishes, at RA365, a point in the circuit for energizing R440. It is noted here and pointed out in detail hereinafter that, if the calling party fails to hang up following the termination of the conversation and after the called party has hung up, the link is automatically released through the line lockout and link release means. In the event the calling party is the first to hang up, R370, which is held operated over the loop extending to the calling substation, restores to interrupt the previously-traced operating circuit for R410. The last-mentioned relay, upon falling back, interrupts, at RA412 and RC413, the holding circuit for R403, which latter relay restores, after an interval, to interrupt, at RA405 and RA406, the operating circuit for R420. When R403 restores, it also removes holding ground from the control conductor C110, thereby to open the holding circuits for the cut-off relay R320 and the switching relay R340. The removal of ground from C110, followed by the restoration of R320, marks the calling line as idle in the bank contacts of the finder and connector switches to which the conductors of this line extend and frees the calling line for seizure on calls incoming thereto. Since the finder switch 380 is of the non-homing type, the wipers thereof remain in the positions to which they are operated during the operation of this switch to find the calling line.

When R420 restores, it opens, at RA427 the operating circuit for R720, which latter relay, upon restoring, stops the operation of the power and supervisory apparatus illustrated in Figs. 6 and 7. At RA421, the relay R420 opens a point in the holding circuits hereinbefore traced for the operated relays R450, R490, R520 and R530 causing these relays to restore. By this same operation, ground is removed from the control conductor C593 to cause the restoration of the cut-off relay associated with the called line, which latter relay, upon restoring, marks the called line 16 as idle in the bank contacts of the connector switches to which the conductors of this line extend.

Immediately upon the restoration of R420, a circuit is completed for energizing the release magnet M566 embodied in the code selecting switch 560, this circuit extending from ground at RA492' by way of C120, RA426, C119, RA359, C121, RA465, RA497', RC498', C195 and through the winding of M566 to battery. This magnet, upon being energized, operates to release the switch and permit the wipers 563 and 564 to return to their normal or home positions, at which time the off-normal springs 571 and 573 are open or returned to normal. With the springs 571 standing in their normal or open circuit positions, the above-traced operating circuit for R490' is interrupted. This relay, upon restoring, completes, at RA497' and RC499', a circuit for ener-

gizing M540 embodied in the rotary switch 550. The circuit noted extends from ground at the switch wiper 585 by way of the multiplied contacts associated with this wiper, C120, RA426, 5 C119, RA359, C121, RA465, RA497, RC499, C196, the self-interrupting contacts associated with MA542 and through the winding of M540 to battery. The magnet M540, in cooperation with the self-interrupting contacts noted, operates, buzzer 10 fashion, to drive the wipers 581 to 585, inclusive, until they reach their respective home positions, at which time the wiper 585 leaves the twenty-fifth contact of the contact set 555 and stands 15 in engagement with the open-circuited first contact of this contact set, corresponding to the normal position of the switch. When the switch wipers of the rotary switch 550 are returned to their respective home positions, ground is removed, at the wiper 585, from C120, which, in 20 turn, completely removes ground from the guard conductor C130, corresponding to the link illustrated, thereby to identify the link as idle in the test contacts of the contact set 675 embodied in the link distributor switch 670. During the 25 sequence of operations just described and when R530 restores, the operating circuit for R400 is interrupted, causing this relay to restore and interrupt the operating circuit for R360, which also restores. With the system in this condition, 30 the link is entirely released and is in readiness for further use.

Operation of the link to establish a connection between two substations connected to the same line

The method by which the apparatus operates to complete a connection on a reverting call is in some respects similar to that just described. Thus, if it be assumed, for example, that a party 35 at the substation A desires to converse with a party having a substation also connected to the line 11 and that the finder connector link illustrated is the link assigned to the calling line, the operation of this link is initiated when the calling party removes his receiver from its hook to start the finder portion of the link operating to 40 search for the calling line. When the calling line is found and dial tone is returned to the calling substation, the calling party may proceed to dial the number of the calling line. As a consequence, the connector portion of the link operates, in accordance with the impulses comprising 45 the first two digits, to select the calling line. Since this line, through the operation of the cut-off relay R320 is marked as busy in the bank contacts of the connector portion of the link, the busy relay R470 is caused to operate immediately 50 the calling line is selected and, upon operating, returns busy tone to the calling subscriber. The calling subscriber disregards the busy signal, however, and proceeds to dial the third digit. As was pointed out above, the code selecting switch 550 responds to the impulses comprising 55 the third digit and operates its wipers 563 and 564 to a position corresponding to the number of impulses making up the third digit. At the conclusion of the digit, the calling party hangs up his receiver to open the loop circuit over which R370 is held operated. This relay, upon 60 restoring, opens the operating circuit for R410, which latter relay, in turn, restores to interrupt the holding circuit for R403 and to apply ground to the control conductor C394 over a path extending from ground at RA412 by way of RC414, RA424, C189, RA493', RC494', RA477, RA493, 65 C186 and the switch wiper 583 to the control conductor noted. Ground on C394 is extended by way of RA312, RC314, RA326, the switch wiper 383, RA345 and RA344 to C110, thereby 70 to provide a multiple holding circuit for R320 and R340, and a circuit for energizing the upper winding of R430 and the winding of R420 in series. The last-mentioned circuit extends from ground on C110 by way of RA506, RC507, C184, through the upper winding of R430, RA402, 75 through the winding of R420 to battery, and is only completed following the restoration of R403, since normally the upper winding of R430 is short-circuited through the operated armatures RA405 and RA406 of R403. The relay R420 is held operated over the above-traced circuit, and R430 operates to complete, at RA434, a holding circuit for itself, which circuit extends from ground at RA421 by way of RC422, C188, RA434 80 and through the lower winding of R430 to battery. At RA435, the relay R430 completes a circuit extending by way of C112 for energizing R350, which, in turn, operates to connect the line conductors C392 and C393 through to the link line conductors C105 and C109, respectively. When R430 operates, it functions to interrupt, 85 at RA433, the application of busy-tone current to the loop extending to the calling subscriber's substation and to prepare, at RA431 and RA432, points in the above-noted circuit for energizing the ringing relay R530. Thereafter, and when ground is applied to C146 at the beginning of a 90 ringing cycle the previously traced circuit for energizing R530 is completed. This relay, upon operating, completes, at RA533, its previously traced holding circuit and operates its armatures RA531 and RA536 to apply ringing current to the calling line by way of the link line conductors C105 and C109. This current is also transmitted to the calling line by way of the rotary switch 95 550 which now stands with its wipers in engagement with the contacts at which the calling line terminates. Obviously, if the signal device at the calling substation is bridged between ground and the same line conductor as the signal device 100 located at the called substation, both of these devices will be energized by the ringing current projected over the selected side of the calling line. If, however, the two signal devices noted are connected between opposite sides of the line and 105 ground, only the signal device located at the called substation will respond to the ringing current.

When either the calling or called party answers following the ringing operation, a circuit 110 is completed for energizing the lower winding of R520, this circuit being identical with that traced above with reference to the operation of the apparatus during a call from the substation A to the substation B. With its lower winding energized, R520 attracts RA524, thereby to complete the previously traced circuit for energizing its upper and lower windings in series. The relay R520 now fully operates, to interrupt, 115 at its armatures RA521 and RA525 and their respective associated contacts RC522 and RC527, the circuit over which ringing current is projected to the signal device at the called subscriber's substation. At these same armatures and their respective associated contacts RC523 and RC526, the relay R520 completes a circuit 120 for energizing R400, this circuit extending from ground at the upper terminal of the lower winding of R400 by way of C108, RA525, C109, RC357, RA355, RA342, the switch wiper 382, C393, the 125

- bridge across C393 and C392 at either the calling or called substation, C392, the switch wiper 381, RA341, RA352, RC354, C105, RA521, RC523, C104 and through the upper winding of R400 to battery. The relay R400, upon operating, opens, at RA402, the holding circuit for R420 and closes, at RA401, the operating circuit for R360. When R420 restores, it interrupts, at RA421, RC422, RA424 and RA427 the holding circuits for R320, R340, R430, R450, R470, R490, R520, R530 and R720, causing these relays to restore. The relay R320, upon restoring, interrupts the operating circuit for R300 and reconnects the windings of the line relay R310 across C392 and C393. Thus, R310 is caused to re-operate and, upon attracting RA311, completes a holding circuit extending by way of RA301 and RC302 for maintaining R300 operated. With the line relay R310 operated, ground at RC313 is applied by way of RA312 to the control conductor C394, associated with the line 11 thereby to maintain this line marked as busy in the bank contacts of the connector switches to which the conductors thereof extend.
- When R430 restores, it interrupts, at RA435, the above-traced operating circuit for R350 causing this relay to restore and, when R520 restores, it interrupts, at its armatures RA521 and RA525, the operating circuit for R400. The relay R400, upon restoring, in turn opens the operating circuit for R360. During the release of the link and when R350 restores, the above-traced circuit for energizing the release magnet M566 embodied in the code selecting switch 560 is completed, thereby to cause the switch 560 to restore to normal, at which time the off-normal springs 571 and 573 are opened. With the springs 571 open, the operating circuit for R490 is interrupted and this relay restores to complete, at RA491' and RC499', the above-traced release circuit for energizing M540 embodied in the rotary switch 550. Thus, the rotary switch 550 is returned to its normal position. When R720 restores the operation of the power and supervisory apparatus is interrupted in the manner previously described. With the apparatus in this condition, the link is entirely released and is in readiness for further use. The line circuit associated with the line 11 however, is held operated until such time as the calling and called parties at the two substations connected to this line hang up. When this occurs, the loop circuit over which R310 is held energized is interrupted and this relay restores to open, at RA311, the holding circuit for R300, causing the latter relay to restore. Thus, the equipment is entirely released.
- From the preceding description it will be apparent that the windings of the relay R400, which are bridged across the link line conductors C104 and C108, form a shunt across the source of ringing current each time this source is connected to project ringing current over a called line. When the called line is other than the calling line the effect of this shunt is reduced to a negligible value by the series connected condensers 591 and 592 inserted in the link line conductors C104 and C108, respectively. These condensers are of approximately .005 microfarads capacitance each, so that the reactance thereof is relatively high at the ringing current frequency and no substantial portion of the ringing current is by-passed by way thereof and the windings of R400.
- The condensers 388 and 390, inserted respec-

tively in the link line conductors C104 and C108, are, on the other hand, relatively large, being of the order of 2 microfarads capacitance each. If, therefore, these last-named condensers were permitted to remain in the ringing circuit, a substantial portion of the ringing current would be shunted through the windings of R400. On reverting calls the line conductors of the line over which ringing current is projected are extended by way of the multiple between the finder and connector bank contacts of the operated link to the armatures RA352 and RA355 of the switching relay R350. In order to eliminate the shunting effect of R400 during the ringing operation it is, therefore, desirable to switch the armatures noted to extend the line conductors of the calling line to the pair of link line conductors C108 and C109, which latter conductors are normally used in the completion of connections routed by way of an outgoing trunk line. As pointed out above this mode of operation is attained by providing means comprising the relay R430 for energizing the switching relay R350 when a calling line is selected by the link on a reverting call.

Operation of the connector switch to select a substation connected to a grounded line

The line having the directory number 38 terminating at the bank contacts of the rotary switch 550 is intended to be of the well-known ground return type. In adapting this type of subscriber's line, commonly employed in rural systems, to the use of automatic switching equipment it has been the practice to employ a line adapter circuit for terminating each grounded line. Several such circuits are well known in the art and since the present invention is not concerned with the form of circuit to be used for terminating the line No. 38 a disclosure of the adapter circuit has been omitted. It is noted, however, that this type of line is usually of the party line variety and that ringing current selection is accomplished through the operation of means provided for this purpose in the adapter circuit. This, of course, means that the impulses of the code selecting digits must be transmitted to the adapter circuit. Hence, a clear metallic circuit extending through the operated link is required when a ground return line is selected, in order that a path shall be available for conducting the dial impulses to the adapter circuit.

In the arrangement shown, such a path is attained by causing the operation of the link line switching relay R350 in response to the selection of the ground return line No. 38 or any other similar line. Assume, for example, that a party at the substation A desires a connection with the substation connected to the line No. 38 and that the link illustrated is the link assigned by the allotted means to the use of the calling line. Following the seizure of the calling line by the finder portion of the link and the receipt of dial tone at the calling substation, the two-digit number 38, identifying the called line, is dialed at the substation A. In response to the impulses of the two digits the switch 550 is operated, in the exact manner described previously, to the position corresponding to the called line. From the preceding description it will be recalled that R450 operates shortly following the end of the first digit and that R480 and R490 operate during the dialing of the second digit. In the present case, immediately the called line No. 38 is selected, a circuit is completed for energizing R510, this cir-

cuit extending from ground at RA421 by way of RC422, C188, the switch wiper 584, C207 and through the winding of R510 to battery. The relay R510, upon operating, prepares, at RA512 a 5 circuit for energizing R500, opens, at RA513, a point in the trunk hunting circuit for R500, and shunts, at RA511, the armature RA504, whereby the busy-tone circuit is held prepared in the event the called line is busy.

10 Shortly following the end of the second digit and when R480 restores to cause the operation of R490, the above-noted operating circuit for R500 is completed, this circuit extending from ground at RA421 by way of RC422, C188, RA512 and through the winding of R500 to battery. The 15 relay R500 now operates to complete at RA509 a circuit for energizing R350, which circuit extends from ground at RA421 by way of RC422, C188, C185, RA473, RC474, RA493, C186, RA509, C187, RA476, C112 and through the winding of R350 20 to battery. The relay R350 upon operating switches the subscriber's line conductors directly through by way of the link line conductors C105 and C109 to the line adapter circuit and 25 the final two digits, comprising the ringing current code selecting digits, may, therefore, be dialed directly into the adapter circuit in the desired manner. When the loop circuit is extended to the adapter circuit associated with the called 30 line, the line and hold relays embodied in the adapter circuit are caused to operate in the usual manner and the last-mentioned relay applies ground by way of the switch wiper 583 to C186, thereby to maintain the link operated. Thus, 35 ground on C186 is extended by way of RA509, C187 and RA476 to C112 to hold R350 energized. Similarly, ground is extended from C186 by way of RA493, RC474 and RA473 to C185, and from C185 to C188 and C110, thereby to maintain energized the relays R320, R340, R450, R490, R500 40 and R510. When R350 operates, the loop circuit holding R370 energized, is obviously broken and this latter relay upon restoring, causes the sequential restoration of R410, R403 and R420. The link remains in this condition until the 45 established connection is cleared out.

It is obvious that the operation of R510 and R500 in the above described sequence of operations in no way affects the busy test circuit extending to R410. Thus, if the called line is busy 50 this busy relay is caused to operate over the exact circuit traced previously and, upon operating, completes the above described circuit for transmitting busy-tone current to the receiver at the calling substation. In addition, this relay functions to open at RA476 and RA473 points in the 55 above-traced operating circuit for R350, thereby to prevent the calling line from being switched through to the busy called line.

The release of a connection as established to 60 the line No. 38 is under the control of the adapter circuit. Thus, when the connection is cleared out ground is removed from the control conductor C186 in the adapter circuit and the operated relays of the link and the line circuit associated 65 with the calling line are caused to restore in a manner which is readily apparent in view of the preceding description. The only departure from the previously described sequence of operations 70 pertains to the restoration of R500 and R510. Obviously the removal of ground from C186, as extended to C110, C185 and C186 results in the interruption of the operating circuits for these two relays along with the other operated relays 75 embodied in the link. Thus, the removal of

ground from C186 results in the complete release of the operated switch train.

Operation of the apparatus to lock out a defective line

5

It is well understood in the art that a faulty line may cause the seizure of one of the finder-connector links and the conditioning of the connector portion of the seized link to respond to impulses transmitted thereto. This condition is 10 also simulated when a party removes his receiver from its hook to complete the associated loop circuit and fails to dial a number. In order to prevent a finder-connector link from permanently being appropriated due to either of these 15 causes, there is provided means comprising the rotary switch 710 and the relays R720, R724, R730 and R735 for releasing the seized link in the event no impulses are transmitted to the connector portion thereof within a predetermined 20 time interval following the seizure thereof and for preventing the line from thereafter being assigned another link until the associated line circuit is restored. Thus, in the sequence of operations just described, if no impulses are transmitted from the calling substation A within a predetermined time interval following the operation of R420, the calling line 11 will be locked out so that no further calls may be completed there-over. In this connection it will be recalled that 25 when the link illustrated is seized, R420 is caused to operate so that a circuit is prepared at RA425 for energizing the line lock-out relay R440. At the same time the power and supervisory apparatus illustrated in Fig. 7, and including the timing device described previously, is started in operation through the application of ground to the start conductor C122 at RA421. A predetermined time interval after this device is started in operation, a ground pulse is applied to C131 30 which causes R440 to operate over a circuit extending from ground on the conductor noted by way of RA443, C111, RA365, C118, RA425 and through the winding of R440 to battery. The relay R440, upon operating, completes a locking 35 circuit for itself which extends from ground at RA421 by way of RC422, C188, RA444, RA443, C117, RA365, C118, RA425 and through the winding of R440 to battery. At its armatures RA441 and RA442, ground from RA425 is substituted for 40 ground from RA442 on C110. This substitute ground is maintained for a predetermined time interval after the operation of R440 at the expiration of which it is removed through the operation of R724. As a consequence, the operating circuit for R420 is interrupted and the holding circuits for R340 and R320 are opened, causing these relays to restore. When R340 restores, it opens, at its armatures RA341 and 45 RA342, the loop circuit over which the line relay R310 is now being held operated. The last-mentioned relay, upon falling back, interrupts the holding circuits for R403 and R410. When R410 restores it opens the holding circuit for R420 causing this relay to restore to interrupt, at RA421, the holding circuit for R490. Thus, all 50 of the relays in the link circuit are restored, ground is removed from the start conductor C122, and the link is in readiness for further use.

When R320 falls back, it recompletes, at RA321 55 and RA322, the loop circuit for the line relay R310, causing this relay to reoperate and complete, at RA311, a holding circuit for the operated lock-out relay R300, this circuit extending from ground at RA311 by way of RA301, RC302, and 60 65 70 75 75

the winding of R300 to battery. With R300 operated, ground is withheld from the start conductor C124, the operating circuit for the cutoff relay is held open at RA304, and ground at RC313 is applied by way of RA312 to the control conductor C394, thereby to mark the calling line 11 as busy in the bank contacts of the connector switches to which this line extends. Thus, it will be seen that the calling line 11 is permanently locked out and that no further calls may be initiated thereover until the loop circuit including the line conductors of this line is opened to initiate the sequential restoration of R310 and R300. If this line is in fact defective, the defect will be detected when the party at the substation A attempts to initiate a call and fails to receive dial tone. When the defect is located and corrected, obviously the two relays noted, namely, R310 and R320, will assume their respective restored positions, in which positions the line circuit is conditioned for further use.

From the preceding description it will be noted that the operating circuit for the lock-out relay R440 is prepared immediately R420 operates and is thereafter under the control of the timing device shown in Fig. 7 until such time as the battery reversing relay R360 operates to open a point in this circuit at RA365. It follows, therefore, that the line lockout apparatus is conditioned to lock out a calling line if for any reason the desired talking connection is not completed within a given time interval following seizure of the link. Thus, if the connector portion of the link is caused to select a busy called line and the calling party fails to hang up within a reasonable time after receiving busy tone the calling line will be locked out and the link released. Again if the called substation is rung but the call is not answered and the calling party holds the connection for an unreasonable length of time the calling line will be locked out and the link released. Obviously in either of the two cases just mentioned the line circuit is restored to normal, following the line lock out operation, when the calling party hangs up.

Operation of the finder-connector link to select an idle trunk outgoing to the office 12

As pointed out in the introductory portion of the specification, provisions are made whereby a calling subscriber, upon the dialing of a predetermined number following the receipt of dial tone, may cause the connector portion of the seized link to select a trunk line outgoing to the exchange 12, in the event an idle trunk line is available. If it be assumed that the line 11 is the calling line, the substation A is the calling substation, and the link illustrated is the link delegated by the allotter means to set up such a connection, the operation of the finder portion of the link to find the calling line and to switch the calling line through to the connector portion of the link is exactly the same as that set forth above. With the arrangement shown, a maximum of three trunk lines may be terminated in the bank contacts of the rotary switch 550 embodied in the connector portion of the link. The conductors of these lines are connected to the twenty-third, twenty-fourth and twenty-fifth contacts, respectively, of the contact sets 551, 552 and 553. Accordingly, it will be understood from the preceding description with reference to the selection of a called subscriber's line terminating at the suboffice 10 that the number identifying the group of three trunk lines out-

going from the exchange 10 is the two-digit number 30. Any two-digit number having a first digit greater than two and a second digit 0 may alternatively be used as a trunk selecting number due to the fact that any first digit comprising more than two impulses will result in the operation of the switch 550 to select the second group of subscribers' lines. When the first digit comprising three or more impulses is dialed at the calling substation A, the wipers of the switch 550 are caused to be operated, in the exact manner described previously, to their respective twelfth off-normal positions and thereafter, when the digit 0 consisting of ten impulses is dialed, the wipers are stepped into engagement with their respective twenty-third contacts. With the switch wiper 584 in this position and shortly following the end of the second digit, a circuit is completed for energizing R500, this circuit extending from ground at RA421 by way of RC422, C188, the switch wiper 584, the twenty-third contact of the contact set 554, C191 and through the winding of R500 to battery. The relay R500, upon operating, opens, at RA504, a point in the above-traced circuit for conducting busy-tone current to the loop extending to the calling subscriber's substation, whereby the calling party will not receive busy tone if the first trunk line of the group is busy. At RA505, the relay R500 prepares a circuit for energizing R490' and at RA509' it prepares a circuit, traced hereinafter, for energizing M540. If the first trunk line 208 of the group is busy, this condition is identified by the presence of ground on the control conductor C210 in the manner pointed out more particularly hereinafter, whereas, if this trunk line is idle, battery is present on C210. Assuming the trunk line to be busy, ground on C210 is extended by way of the switch wiper 583, C188, RC498, RA494, to RA455, thereby to complete a circuit for energizing R470. The relay R470, upon operating, prepares, at RA478, a further point in the above-noted circuit for energizing M540 embodied in the rotary switch 550. This circuit is subsequently completed upon the operation of R650, included in the power and supervisory apparatus illustrated in Figs. 6 and 7, and extends from ground at RA651 by way of C189, RA478, C192, RA513, RA509', C190 and through the winding of M540 to battery. When the above-traced circuit is thereafter interrupted upon the restoration of R650, the magnet M540 steps the wipers of the switch 550 from engagement with the contacts terminating the trunk line 208 and into engagement with the contacts terminating the next succeeding trunk line. If this second trunk line is also busy ground will be retained on the switch wiper 583 so that the relay R470 is held operated. Shortly thereafter, and due to the continuous cyclic operation of R655 and R659, a second ground pulse is transmitted over the above-traced operating circuit for energizing M540, which pulse causes this magnet to step the wipers from engagement with the contacts terminating the second trunk line and into engagement with the trunk line terminating the conductors of the third and last trunk line. If this last trunk line is also busy, the relay R470 is held operated so that the third ground pulse transmitted to M540 causes the wipers of the switch 550 to be stepped into engagement with their respective associated first contacts. When this occurs, the previously-traced operating circuit for R500 is interrupted at the switch wiper 75

584, causing this relay to restore to interrupt, at RA509', the operating circuit for M540 and to complete, at RA504, the previously traced path for conducting busy-tone current to the loop extending to the calling subscriber's substation. Thus, the calling subscriber is informed that all of the trunk lines are busy and that the connection can not, at the moment, be completed. It will be noted that, with the equipment in this 10 condition, the release of the link is initiated when the calling subscriber restores his receiver to its hook and that the operations which occur during the release of the link are exactly the same as those described in a preceding portion of the 15 specification.

During the above-described operation of the switch 550 to test the condition of the trunk lines outgoing therefrom, the ground pulses applied to C190 are extended by way of RC499' 20 and RA498 to RA484, thereby to maintain the slow-to-release relay R480 operated during the testing of the trunk lines. If one of the lines is found idle during the testing operation, such, for example, as the line 208, the relay R470 is caused 25 to restore immediately the line is selected, thereby to interrupt, at RA478, the operating circuit for M540 and to prevent further hunting operations on the part of the switch 550. Since no further pulses are thereafter applied to C190, R480 30 restores after an interval to interrupt, at RA481 and RC482, the operating circuit for R460 and to complete, at RA481 and RC483, the previously traced operating circuit for R490. The relay R490, upon operating, completes, at RA497, the 35 previously traced locking circuit for itself and, at RA493, completes a path for applying ground to the control conductor C210 of the selected trunk. This path extends from ground at RA421 by way of RC422, C188, C185, RA473, 40 RC474, RA493, C186 and the switch wiper 583 to the control conductor C210. It will be understood that, with the wipers of the switch 550 standing in any one of the three positions corresponding to one of the outgoing trunk lines, 45 R500 is held energized. With R500 energized, a circuit is prepared, at RA505, for energizing R490', which circuit is completed upon the operation of R490, this circuit extending from ground at RA481 by way of RC483, RA491, C183, RA505, C178 and through the winding of R490' to battery. With R500 operated and R470 restored, a 50 circuit is also completed, upon the operation of R490, for energizing the slow-to-operate switching relay R350, this circuit extending from ground at RA421 by way of RC422, C188, C185, RA473, RC474, RA493, C186, RA509, C187, 55 RA476, C112 and through the winding of R350 to battery.

The relay R350, upon operating, applies, at 60 RA359', multiple ground to the start conductor C122, thereby to maintain the power and supervisory apparatus operating and, at its armatures RA352 and RA355 and their respective associated contacts RC354 and RC357, substitutes the link line conductors C105 and C109 for the link line conductors C104 and C108, thereby to complete a clear metallic loop circuit by way of the conductors C105 and C109 and the trunk conductors C208' and C209 to the two-way repeater 65 inserted in the trunk line extending to the exchange 12. This operation, as will be pointed out more specifically hereinafter, causes ground to be applied to the control conductor C210 in the repeater circuit, which ground is extended 70 back by way of the switch wiper 583, C186, RA493,

RC474, RA473, C185, RA508, and RA506 to C110, thereby to maintain operated the relays R340, R320 and R300. This ground being present on C185 and C188 maintains R450, R490, R350, and R500 energized. With R490 and R500 operated, 5 the previously traced operating circuit for R490' is maintained complete. Thus, the connection is extended from the calling line to the repeater circuit illustrated in Figs. 8 and 9, which circuit operates in the manner pointed out in detail 10 hereinafter, to extend the connection to the manual office 12.

During the above-described sequence of operations and when the switching relay R350 operates, the loop circuit holding R370 operated is 15 broken at RA352 and RA355. The relay R370, upon restoring opens, at RA371, the holding circuit for R410, which latter relay restores to open the holding circuit for R403. The relay R403, in turn, restores after an interval, to open 20 the holding circuit for R420. When R420 falls back it removes, at RA421 and RC422 multiple ground from C188 and C185, whereby the switch train is held operated only by the ground returned to these conductors from the repeater circuit 25 associated with the selected trunk line.

It is pointed out that with the link in this condition the lock-out relay is rendered ineffective to cause the calling line to be locked out for the reason that the operating circuit for this relay is 30 now open at RA425.

The release of the switch train following the seizure of one of the trunk lines outgoing from the exchange 10 in the manner just described is accomplished through the removal of ground 35 from the control conductor of the seized line, such, for example, as the conductor C210 embodied in the trunk line 208. As pointed out in the description set forth hereinafter with reference to the operation of the repeater circuit illustrated in Figs. 8 and 9, the removal of ground from the control conductor of the seized trunk line to initiate the release of the switch train is under the control of the calling party until the connection is cut through by way of the seized 40 trunk line to the exchange 12 and a talking connection has been established between the calling substation and the operator in the distant exchange. If and when such a connection is established, the release of the repeater and the switch 45 train preceding the repeater is under the control of the operator in the distant exchange. In any case, when the ground is removed from the control conductor of the outgoing trunk, the completed circuits for the various operated relays, 50 all of which circuits include the conductor C186, are interrupted. As a result these relays, namely R300, R320, R340, R350, R450, R490, R490', and R500, are caused to restore, thereby to release 55 the link and the line circuit associated with the calling line, at which time the equipment is completely restored to normal and is in readiness for further use.

Operation of the repeater circuit to extend a connection to the manual exchange 12

By way of completing the disclosure, the operation of the repeater circuit illustrated in Figs. 8 and 9 and the equipment terminating the outgoing trunk line illustrated in Fig. 10 will now 70 be considered. If it be assumed that the trunk line 208 is seized in the manner just described on a call from the substation A to a line terminating at the manual exchange 12, the repeater illustrated in Figs. 8 and 9 operates im- 75

- mediately upon seizure of the trunk line to switch the connection through and signal the operator in the distant exchange. Thus, immediately this trunk line is seized, the loop extending to the calling substation A is connected through to the repeater so that a bridge circuit including the line conductors C208' and C208 is completed for energizing the line relay R850. This relay, upon operating, completes, at RA851, a circuit for energizing the slow-to-release relay R820, this circuit extending from ground at RA835 by way of RC937, RA952', C828, RA851, RC848, RA847 and through the winding of R820 to battery. At RA852, the relay R850 completes a circuit for energizing R910 and R940 in parallel, this circuit extending from ground at RA852 by way of C833, RA853 and RC855 to RA927, where the circuit divides, one branch extending through the winding of R910 to battery and the other branch extending by way of RA925, RC926' and through the winding of R940 to battery.
- When R820 operates, it short-circuits, at RA823 and RC825, the winding 882 of the repeater 880 and prepares, at RA821, a circuit for applying ring-back tone voltage across the loop extending to the calling subscriber's substation. The relay R940, upon operating, opens, at RA944, a point in the operating circuit for R950 and, at RA948, completes a path for extending ground from the lower winding of the impedance element 970 and C855 to the control conductor C210 of the trunk 208, thereby to hold operated the link preceding the repeater in the manner just described. It will be observed that this path is extended by way of C857 and RA802 to the control conductor noted. At its armatures RA941 and RA945, and their respective associated contacts RC943 and RC947, the relay R940 applies ringing current to the loop extending by way of the outgoing trunk to the operator's board in the distant manual exchange. The path of this current extends from one terminal of the ringing current generator by way of the resistor 949, RC943, RA941, RA962, C816, the repeater winding 883, C807, the switch springs 1003 and 1005, C1012, the repeater winding 1041, the condenser 1043, the repeater winding 1042, C1013, the switch springs 1004 and 1006, C819, the repeater winding 884, C817, RA964, RA945, and RC947 to the opposite terminal of the ringing current generator. Current flowing in the above-traced circuit causes an induced current to flow through the winding of the alternating current relay R1050 over the closed circuit including C1014, the condenser 1063, the winding of R1050, RA1061, C1015, and the repeater windings 1044 and 1045 connected in series with the condenser 1046 across the conductors C1014 and C1015. The relay R1050 now operates and, as indicated by the mechanical link 1062, is maintained operated pending energization of R1060. In its operated position, an obvious circuit is completed at RA1051 for energizing the signal lamp 1047, thereby to indicate to the operator in the manual exchange that an incoming call on the trunk line noted awaits attention. During the ringing operation, ring-back tone current is conducted by way of the conductor C991, the condenser 992, RA961', C806, RA821 and the loop circuit extending to the calling substation to produce a tone in the receiver at this substation indicating that the operator at the manual exchange is being signalled.
- Simultaneously with the operation of R946,

the relay R910 operates to attract RA911. As indicated, one of the contact springs associated with RA911 is weighted so that it operates, pendulum fashion, to prevent a circuit, including the same, from being completed for any substantial time interval until the vibrations of the weighted spring have died out. The springs under the control of this armature are included in the circuit for energizing the upper winding of the slow-to-operate relay R930, but, due to the described pendulum action and the slow-to-operate characteristic of the relay noted, this relay does not operate immediately following the operation of R910. When the vibration of the weighted spring associated with RA911 ceases, the above-noted circuit is completed. This circuit extends from ground at RA911 by way of RA932, RC933 and through the upper winding of R930 to battery. The relay R930, upon operating, completes, at RA931, a circuit for conducting pay station tone current to the loop extending to the terminating equipment in the distant exchange. Thus, as was pointed out previously, if a call is initiated on a pay station line terminating at the exchange 10, pay station tone current is connected to the control conductor of the seized link. Hence, when the connection is extended to the trunk line illustrated, pay station tone current is caused to flow by way of C210, RA802, C857, RA948, C855 and through the lower winding of the impedance element 970. An induced voltage is, therefore, developed across the upper winding of the element 970, which voltage is impressed on the line conductors C807 and C819 over a path extending by way of RA931, RA951, and the condenser 868, when the relay R930 operates. This voltage is maintained on the line conductors noted until after the call is answered by the operator in the distant manual exchange, thus indicating to the operator that the call originated on a pay station line terminating at the exchange 10.

The relay R930, upon operating, interrupts, at RA932 and RC933, the above-traced circuit over which it was initially energized and prepares, at RA932 and RC934, a circuit for energizing the slow-to-operate relay R950. It is noted that the interruption of the operating circuit for R930 does not cause this relay to restore since, upon operating, it opens, at RA935 and RC937, the obvious path normally short-circuiting its lower winding, permitting its lower winding to be energized in series with the winding of R820. Hence, the two relays R930 and R820 are maintained operated, due to the continued energization of the two windings noted in series. When R930 operates it also completes, at RA935 and RC936, an obvious circuit for energizing R920, which latter relay now operates to open, at RA921, a point in the above-traced circuit for energizing R840 and to open, at RA927, the previously traced operating circuit for R910 and R940. At RA922 and RA925, the relay R920 prepares an alternative operating circuit for energizing R910, which circuit is described in detail hereinafter. At RA927', the relay R920 prepares a circuit for energizing R810 and, at its armature RA929', it completes an obvious alternate path for applying ground from the lower winding of the impedance element 970 by way of the control conductor C857 to the control conductor C210. At RA928, the relay R920 opens a point in the path for applying battery from the resistor 913 to the control conductor just mentioned, this battery potential normally being utilized to identify the 75

- trunk line as idle in the bank contacts of the connector portions of the various links at which the trunk line terminates. In view of the preceding description, it will be understood that the 5 presence of battery on the control conductor noted permitted the seizure of the trunk line and, further, that with the repeater in the condition described, wherein ground is present on the control conductor C210, this trunk line is marked as busy.
- 10 At RA925', the relay R920 prepares a circuit, traced hereinafter, for energizing the trunk release relay R800, the operation of which is pointed out with greater particularity hereinafter.

Immediately upon the operation of R920, R910 15 restores to open, at RA911, a further point in the operating circuit for R930 and a point in the prepared circuit for R950. Shortly thereafter, the slow-to-release relay R940 restores to discontinue the application for ringing current to the 20 loop extending to the operator's equipment in the manual exchange and to prepare, at RA944, a further point in the operating circuit for R950. At RA948, the relay R940 opens the multiple path for applying ground from the lower winding of 25 the impedance element 970 to the control conductor C857. With the repeater in this condition, no further operations occur until the connection as extended to the manual exchange is answered by the operator, provided, however, that the call 30 is answered within a predetermined time interval.

When the operator in the exchange 12 answers the call by inserting the plug terminating her telephone set in the jack 1070, battery as conventionally connected between the tip and sleeve 35 contacts of the inserted plug is included in a circuit for energizing the upper winding of R1020, this circuit extending from one side of battery on the contact 1071 by way of C1014, the repeater winding 1044, RC1022, RA1021, the upper winding 40 of R1020, RA1031, the repeater winding 1045 and C1015 to the opposite terminal of battery at the contact 1072. The relay R1020 operates in response to the energization of its upper winding to complete, at RA1021, an obvious circuit for 45 energizing R1060, which latter relay operates to open, at RA1051, the circuit for energizing the signal lamp 1047 and to open, at RA1061, a point in the operating circuit for R1050.

At RA1025 and RA1026, the relay R1020 completes a circuit for energizing the lower winding of R1020, this circuit extending from ground on the sleeve contact 1073 of the jack 1070 by way of the two armatures noted and through the lower winding of R1020 to battery. At RA1021, the relay R1020 short-circuits its upper winding, thereby to render itself slightly slow to release. The operation of RA1021 further results in the connection of the resistor 1028 in shunt with the condenser 1046. At RA1024, the relay R1020 completes a circuit for energizing the polarized relay R1030 in series with R900 and R830, this circuit extending from ground at the lower terminal of the winding of R900 by way of this winding, RC946, RA945, RA964, C817, the repeater winding 884, C819, the switch springs 1006 and 1004, C1013, the repeater winding 1042, RA1024, the two windings of R1030 in series, the repeater winding 1041, C1012, switch springs 1005 and 70 1003, C807, the repeater winding 883, C816, RA962, RA941, RC942, C808 and through the winding of R830 to battery. When the above-traced circuit is completed, R1030 operates to open, at RA1031, the circuit connecting the resistor 1028 in shunt with the condenser 1046.

The relay R830, upon operating, completes, at RA831, an obvious circuit for energizing R870. Simultaneously with the operation of R830, R900 operates to complete, at RA902 and RC903, the above-noted alternative operating circuit for 5 R910, which circuit extends from ground, at RA902, by way of RC903, RA922, RC923, RC926, RA925 and through the winding of R910 to battery. The relay R910 now reoperates to again cause vibration of the weighted armature spring 10 RA911. After an interval sufficient for this spring to settle into resting engagement with the associated contact spring, the above-noted operating circuit for R950, which extends by way of RA932, RC934 and RA944, is completed. After 15 a further time interval, R950 operates to interrupt, at RA951, the above-traced path for applying pay station tone to the loop extending to the manual exchange. It is noted that the delayed operation of R950 permits this tone to be received by the manual operator for a short time interval after the incoming call is answered. At its armatures RA952 and RA952', the relay R950 opens a point in the above-traced holding circuit for R820 and completes an obvious alternative 20 holding circuit for R930 to maintain the last-mentioned relay operated. At RA953, the relay R950 completes a circuit for energizing the battery reversing relay R960, this circuit extending from ground at RA852 by way of C833, RA953, 30 RC954 and through the winding of R960 to battery. At RA956, the relay RA950 completes a circuit for energizing the battery reversing relay R810, which circuit extends from ground at RA927' by way of RC928, RA956, RC957, C854 35 and through the winding of R810 to battery. At RA959, the relay R950 completes an obvious path for short-circuiting the lower winding of the impedance element 970, thereby to eliminate any possibility of pay station tone being impressed 40 on the talking circuit.

The battery reversing relay R960, upon operating, reverses in an obvious manner the path of the current flowing through the polarized relay R1030 causing the latter relay to restore. At 45 RA965, the relay R960 completes a holding circuit for itself, which circuit extends from ground at RA852 by way of C833, RA965, C839, RC863, RA861, C836 and through the winding of R960 to battery. At RA966, the relay R960, upon operating, completes an alternate circuit extending by way of C835 for energizing the slow-to-release relay R870. The relay R870, upon operating, prepares, at RA872, a point in the circuit for energizing R840 and completes, at RA873 and 50 RC874, a connection between the grounded control conductor C855 and the control conductor C857. At RA871, the relay R870 completes an obvious circuit for energizing the lower winding of the polarized relay R860. It is noted that this last-mentioned relay does not operate when its lower winding is alone energized but is only thereby conditioned to operate when its upper winding is thereafter energized.

When R810 operates in response to the operation of R950, it functions in an obvious manner to reverse battery back over the loop extending to the calling substation through the operation of its armatures RA811 to RA814, inclusive. 70 This battery reversal may be utilized for supervisory or metering purposes, if desired. A further consequence of the operation of R950, as was noted above, is the restoration of R820, which relay, upon restoring, opens, at RA821, a further 75

- point in the ring-back tone circuit described above and disconnects, at RA822, battery as applied to the resistor 827 from the upper terminal of the winding of R830. With R820 restored, 5 the by-pass condenser 828 is connected in shunt with the windings of the line relay R850 so that a low impedance path is completed for voice frequency currents conducted over the loop extending to the calling subscriber's substation.
- 10 With R830 energized, a point is opened, at RA832, in the circuit for energizing the repeater release relay R800. With the apparatus illustrated in Figs. 8, 9 and 10 in this condition, a talking loop is established between the calling substation and the operator's telephone so that the operator and the calling subscriber may converse as desired. The operator, upon receiving the information from the calling party as to the desired line, may proceed to extend the connection to this desired line in a manner well known in the art, it being understood that the extension of the connection in no way affects the condition of the apparatus illustrated in the three figures noted.
- 15 When a connection is once established by way of the repeater and the operator's equipment as shown in Fig. 10, it can be released by the operator's withdrawal of the connecting plug from the jack 1070. Thus, so long as the plug is maintained 20 in the jack, R1020 is held operated to maintain closed the previously traced operating circuit for R900 and R830. Hence, the only operations which occur when the calling subscriber hangs up prior to a clearing out of the connection at the 25 operator's position are the restoration of the line relay R850, followed by the restoration of the battery reversing relay R960. When, however, the connection is cleared out at the operator's station after the loop circuit has been opened at the 30 calling substation, R830 and R900 are caused to restore. R830, upon restoring, opens, at RA831, the multiple circuit for R870 and again prepares the circuit for energizing R800. When R900 restores, it opens, at RA902, the above-described 35 operating circuit for R910. The relay R910, in turn, restores to open the circuit holding R950 operated, which latter relay, upon restoring, opens the operating circuit for R930. When R930 falls back, it opens the operating circuit of R920. While the above operations are taking place, R870 falls back and, with R870, R920 and R940 restored, ground is completely removed 40 from the control conductor C857 so that the switch train preceding the repeater is caused to restore in the manner described previously.
- 45 It is pointed out that if the connection is cleared out at the operator's station and is held at the calling end thereof, the switch train preceding the repeater is maintained operated and the trunk line including the repeater is held marked as busy in the bank contacts of the connector switches to which this line extends. Thus, when R960 is once operated, it is held operated over the holding circuit, traced above, so long as the line relay R850 is maintained energized. With R960 operated, the operating circuit for R870 is maintained complete and, with the last-mentioned relay operated, ground from the lower winding of the impedance element 970 is maintained 50 on the control conductor C857. Hence, the switch train is held operated and the trunk line is marked as busy. It will be seen, however, that when the loop is thereafter opened at the 55 calling substation to cause the restoration of

R850, the relay R900 restores to open the holding circuit for R870, which latter relay, upon restoring, removes ground from C857 to initiate the release of the switch train preceding the repeater and to mark the trunk line including this repeater as idle through the application of battery to the control conductor noted from the resistor 818.

60 In the operation of the repeater to extend a connection to the operator's board in the distant manual exchange 12, it is assumed that the operator answers the call within a predetermined time interval after the repeater is seized. Provisions are made whereby, in the event the operator fails to answer the call, the switch train 65 and the repeater are caused to be released so that the equipment will not be uselessly tied up for prolonged time intervals. Thus, in the sequence of operations just described, the relay R920, upon operating, prepares, at RA825', a 70 circuit for energizing the release relay R800. This circuit includes a time pulse conductor C896 which corresponds to the conductor C137 leading from the power and supervisory apparatus illustrated in Fig. 7 in that it is connected to a timing 75 device which applies a ground pulse thereto a predetermined time interval after the repeater is taken for use. Now, if the call is answered within the predetermined time interval required for the ground pulse to be applied to the conductor C896, the relay R800 is caused to operate, 80 in the manner described above, to open a point in the above-traced circuit so that any ground pulses applied to C896 are without effect. If, however, the operator fails to answer the call 85 within the said predetermined time interval, ground as applied to C896 by the timing device associated therewith completes a circuit for energizing R800, this circuit extending from ground on C896 by way of RA804, RA832, C858, RA925', 90 C859 and through the winding of R800 to battery. The relay R800, upon operating, disconnects, at its armatures RA801 and RA802, the control conductor C210 of the trunk line C208 from the control conductor C857 of the repeater 95 and connects this control conductor to the cutoff ground conductor C887, which corresponds to C148 the conductor leading from the timing device incorporated in the power and supervisory apparatus illustrated in Fig. 7. At its armatures RA803 and RA804, the relay R800, upon operating, completes a holding circuit for itself which also extends from ground on the conductor C857 and is otherwise exactly the same as the operating circuit for this relay. After a further time 100 interval, ground is removed from C857 at the timing device so that ground is no longer present on the control conductor C210. Hence, the switch train involving the operated finder-connector link is released thereby to cause the relays including the release relay R800 in the repeater to restore. Immediately the seized finder-connector link starts to release, the loop circuit over which the line relay R850 is held operated is opened, causing this relay to restore. When R850 105 restores its armatures under the conditions assumed, wherein the connection is not completed to the operator's station, all of the operated relays incorporated in the repeater illustrated are caused to restore. Thus, not only is the finder-connector link involved in the partially established connection returned to its normal position, but the repeater is also released and conditioned for further use.

Operation of the apparatus to complete a connection on a call from the exchange 12 to the exchange 10

5 The trunk line illustrated is taken for use on a call to be extended from the exchange 12 to the exchange 10 by the insertion of the plug terminating the operator's telephone in the jack 1070. As a result, the relay R1020 is caused to operate over the circuit traced previously and in turn completes the above traced circuit for energizing R830, R900 and R1030 in series. Since R960 is, under the conditions noted, in its restored position, the current flowing through R1030 is in a direction such that this relay is also caused to operate. The relay R830, upon operating, completes, at RA831, the above traced circuit for energizing R870 and opens, at RA832, a point in the circuit for energizing R800. The relay R900, upon operating, prepares, at RA901, a loop extending to the exchange 10 and, at its armature RA902, completes a multiple circuit for maintaining R870 energized. The last-mentioned relay, upon operating, completes, at RA871, a circuit for energizing the lower winding of the polarized relay R860 and, at RA872, completes a circuit for energizing R840, which latter circuit extends from ground, at RA921, by way of C818, RA872, and the winding of R840 to battery. At RA873, the relay R870, upon operating, applies ground from the lower winding of the impedance element 970 to the control conductor C857, thereby to mark the trunk line over which the call is being extended as busy in the bank contacts of the connector switches at which this line is terminated.

When R840 operates, it completes, at its armatures RA841, RA842 and RA846, the loop circuit, extending by way of the line conductors C809 and C868 and forming the cable 100, to the line circuit 387. This circuit includes the line conductor C809 and extends by way of RA901, C815, RA841, C864, the repeater winding 881, C865, RA842, RC844, the upper winding of R860, the resistor 853, the repeater winding 882, C867 and RA846 to the opposite line conductor C868. Through the operation of this line circuit 387, the trunk line noted is connected through to the bank contacts of the finder switches at which this line terminates. When the line circuit operates, a link is assigned to the use of the calling trunk line and assuming that the link illustrated is the one delegated to the use of the trunk line, the finder switch incorporated therein is caused to operate, in the exact manner described previously, to find the calling trunk line and extend the loop circuit through to the connector portion of the link. Following the seizure of the calling trunk line, the connector portion of the link is conditioned 60 to respond to impulses transmitted from the impulsive device 1010 associated with the trunk line illustrated.

As pointed out above, the relay R840, upon operating disconnects, at its armatures RA842 and RA845, the windings of the line relay R850 from the line conductors C865 and C866. At RA842 and RC844, a circuit is completed upon the operation of R840 for energizing the upper winding of R860, which circuit includes the line conductors extending to the line circuit 387, the windings of the line relay embodied in this circuit in series with battery, and the resistor 853. The relay R860 does not operate, however, since the polarity of the current flow through the upper winding thereof is now reversed to

that required for causing operation of this relay. At RA847 and RC848, the relay R840 prepares a circuit, traced hereinafter, for energizing R820.

Following the operation of R840, no further operations occur in the repeater circuit until impulsive is started at the operator's station. In this connection, it will be understood that the seized finder switch, upon extending the connection to the associated connector switch, 10 causes dial tone to be returned over the loop to the operator's telephone, thereby to indicate that the seized link is in a condition to respond to impulses transmitted from the operator's station. In order to complete the impulsive circuit, 15 the operator actuates the key switch 1000 to its off-normal position, in which position the line conductors C807 and C819 are connected to the impulsive springs 1011. These springs, which are normally closed, maintain complete the circuit holding R900 and R830 energized.

During impulsive, R900 follows the impulses and repeats the same over the loop extending to the seized finder-connector link through its operation to open the loop circuit at its armature RA901. Thus, each time the springs 1011 are opened, the operating circuit for R830 and R900 is interrupted, causing the last-named relay to restore, thereby to open, at RA901, the loop circuit to the line relay R370 embodied in the seized link. Conversely, when the springs 1011 are closed at the end of each impulse, R900 is caused to reoperate. At the beginning of the first impulse of each digit, when R900 restores, the above-noted operating circuit for R820 is completed, this circuit extending from ground at RA902, by way of RC904, C834, RC848, RA847 and through the winding of R820 to battery. The relay R820, upon operating, short-circuits, at RA823 and RC825, the lower winding 882 of the repeater 880, thereby to improve the impulsive circuit extending to the seized finder-connector link by decreasing the resistance in this circuit. At this same armature and its associated contact RC824, the condenser 826 shunting the upper winding of R860 is disconnected. At RA822, the relay R820 completes an obvious circuit for holding R830 energized during impulsive. It will be understood that R820, due to its slow-to-release characteristic, remains energized throughout each series of impulses. Shortly following the conclusion of each digit, R820 restores to open the path short-circuiting the winding 882 and to again connect the voice frequency by-pass condenser 826 in shunt with the upper winding of R860, thereby to provide a low impedance path for voice frequency currents.

The mode of operation of the connector switch embodied in the seized link to select and test the called line is exactly the same as that set forth above in the description with reference to a call initiated on the line 11. From the preceding description, it will be understood that, if the called line is found busy, busy tone will be returned over the trunk line and through the repeater illustrated to the operator in the distant manual exchange to indicate that the desired connection can not be completed. It will further be understood that, in order to receive such a signal, the operator will, immediately following the impulsive, return the key switch 1000 to its normal position so that the busy signal will be extended to her telephone. The operator may then initiate the release of the connection by withdrawing the plug ter- 75

minating her telephone set from the jack 1070, thereby to open the circuit holding the relays R830 and R900 operated, which relays, upon falling back, cause the remaining operated relays R840, R860, R870 and R960 to be restored in an obvious manner.

In the event the call is answered at the called substation, a conversational circuit is set up between the called telephone and the operator's telephone, which may be extended in a conventional manner to a calling line terminating at the manual exchange. In response to the completion of the talking loop the battery reversing relay R360 of the operated link is caused to operate in the manner described previously, thereby to reverse the polarity of the current flowing over the loop and through the upper winding of R860. This upper winding is now correctly energized to cause the operation of R860.

When R860 operates, it completes, at RA861 and RC862, an obvious circuit extending from ground at RC862 for energizing the battery reversing relay R960, which latter relay, upon operating, reverses the flow of current through the windings of R1030, thereby causing this relay to restore. The relay R960, upon operating, further functions to open, at RA961', a point in the ring-back tone circuit described previously and to complete, at RA966, a multiple circuit for maintaining R870 operated.

Before describing the release of the connection as established by way of one of the trunk lines, it is pointed out that the line lockout apparatus, as incorporated in the operated link, is effective to lock out the trunk line over which the connection is extended and to release the operated link in the event the desired connection is not completed within a reasonable time after the link is seized. In this connection, it is pointed out above that the line circuit 387 terminating the incoming end of the trunk line is identical with that terminating the subscriber's line 11 in that it includes a line relay, a cut-off relay and a lockout relay, all connected and arranged in the same manner as the relays R310, R320, and R300 associated with the line 11. Hence, these relays are susceptible of being controlled by the relay R440 to cause the trunk line 208 to be locked out in the exact manner described previously with reference to the subscriber's line noted. In so far as the operation of the link release and line lockout apparatus is concerned it is, therefore, of no consequence that the calling line is a trunk line rather than a subscriber's line.

The release of a connection as set up in the manner described in the immediately preceding paragraphs is entirely under the control of the operator located in the distant exchange. Thus, so long as the loop circuit is held completed at the operator's station, the two relays R830 and R900 are maintained in an energized condition, which means, of course, that the other operated relays, namely, R840, R860 and R870 are held operated. With R840 and R900 operated the loop circuit extending to the seized link is held closed and hence the link is maintained in its operated condition. If, therefore, the called party hangs up before the connection is cleared out at the manual exchange 12, the only operations which occur are the restoration of the battery reversing relay R370 followed by the sequential restoration of R860 and R960, and the reoperation of R1030. Thereafter and when the connection is cleared out at the manual exchange 12, the relays R830 and R900 are caused to restore. The relay R830, upon re-

storing opens the operating circuit for R870. When R870 falls back, ground is removed from the control conductor C857 so that the trunk line illustrated is no longer marked as busy in the bank contacts of the connector switches located in the exchange 10. When R870 restores it also opens, at RA872, the operating circuit for R840 causing this latter relay to restore. With the relays noted deenergized, the repeater is entirely released and is in readiness for further use. It will be understood that, upon the restoration of R900, the loop circuit extending to the operated finder-connector link is opened, and this link is, accordingly, caused to release in the exact manner described previously.

In the event the connection is cleared out at the manual exchange 12 before it is released at the called substation, R830 and R900 restore and the last-mentioned relay opens the loop circuit extending to the operated link thereby to initiate the release of the link in the manner described previously. With this loop circuit open, R860 restores to cause the restoration of R960. When R960 falls back the operating circuit for R870 is opened and the latter relay, in turn, opens the operating circuit for R840 and removes ground from the control conductor C857. Thus, the repeater is entirely released and the trunk line is marked as idle in the bank contacts of the connector switches at which this line terminates.

Operation of the testing apparatus

In order to check the condition of the power and supervisory apparatus located in the exchange 10 from the supervisor's desk located in the exchange 12, a connection may be established by way of one of the trunk lines interconnecting the two exchanges to one of the links embodied in the exchange 10 in the exact manner described in the immediately preceding paragraphs. Assuming that the link illustrated is seized the operator in the exchange 12 upon hearing dial tone, may proceed to dial the test number which comprises a single digit of two impulses. It is to be observed that the number of impulses comprising this test digit is intermediate the predetermined number of impulses comprising the digit required for selecting the first group of subscribers' lines and the greater number of impulses comprising the digit required for selecting the second group of subscribers' lines. The dialed impulses are repeated through the operation of R900 to the connector portion of the operated link and cause the wipers of the switch 550 to be stepped to their respective second off-normal positions. From the preceding description it will be recalled that during impulsing the two relays R480 and R460 are caused to operate in the order named. Shortly following the end of the digit these two relays restore, the last-mentioned thereof completing at RA464 a circuit for energizing R500, this circuit extending from ground at RA421 by way of RC422, C188, the switch wiper 584, the third contact of the contact set 554, C193, RA456, RA464, C191, and through the winding of R500 to battery. The relay R500 now operates to connect at RA501 and RC503, the conductor C177, to the alarm conductor C152. As a result there is completed a path for transmitting alarm tone over the established loop to the supervisor's telephone located in the exchange 12. If the power and supervisory apparatus is operating properly so that C152 is connected to the ringing current conductor C156, this condition will be indicated through the receipt of a tone corre-

sponding to the voltage applied to this ringing conductor. The path of the current for producing this tone extends from the ringing conductor noted by way of RCT52, RA751, C152, RC503, 5 RA501, C177, RA451, RA404, C106, the condenser 389, RA364, over one side of the established loop to the manual office, through the receiver at the calling substation, back over the other side of the loop, RA352, RC353, RA362 and through the up- 10 per winding of R370 and battery to the other side of the ringing current source. If for some reason the power and supervisory apparatus is not operating, obviously no voltage will be applied to C152, and the attendant, failing to hear any tone will 15 recognize that trouble is present in the apparatus at the exchange 10. Similarly, if for some reason R750 has been caused to operate due to a fault in some portion of the power and supervisory apparatus, a tone will be received corresponding to 20 the ringing voltage impressed on C155, thus indicating to the attendant that the power and supervisory apparatus is out of order. Obviously the same test may be performed by way of any one of the subscriber's lines terminating at the ex- 25 change 10, the function of the apparatus involved being exactly the same as that just described.

From the foregoing description it will be apparent that the second off-normal position of the switch 550 corresponds to one of the subscriber's 30 lines, namely, the line 11, and also to the source of alarm tone current connected to the conductor C152. Whether the line 11 or the source is selected depends upon whether this predetermined operating position of the switch is reached in 35 response to the impulses of a single digit or in response to the impulses of two digits. To summarize, if a single digit of two impulses is dialed into the connector switch, the link line incoming to the switch is connected to the alarm tone current source. If, on the other hand, two digits 40 each comprising a single impulse, so that the sum total of impulses is two, are dialed into the connector switch, the line 11 is selected. The selection of the line 11 in preference to the alarm tone current source when two single impulse digits are 45 dialed is due to the operation of R450 to open the operating circuit for R500 at the end of the first digit. Where a single digit of two impulses is dialed, the relay R450 does not operate, for reasons pointed out above, and, hence, R500 is 50 permitted to operate to connect C152 to the loop extending to the calling sub-station.

While there has been described what is at present considered to be the preferred embodiment of 55 the invention, it will be understood that various modifications may be made therein and it is contemplated in the appended claims to cover all such modifications as fall within the true spirit and scope of the invention.

60 I claim:

1. In an automatic telephone system, a plurality of subscribers' lines, a plurality of trunk lines, a plurality of finder-connector links for setting up connections between said lines, at least 65 a portion of said links having access to said trunk lines, allotter means for assigning said links for use in a definite order, the finder portion of each link assigned for use being effective to search for and seize a calling one of said lines, a source of 70 ringing current, a plurality of ringing current conductors each adapted to be connected to said source, a switch, control means for said switch, means including said switch for controlling the connection of said conductors to said source so 75 that each thereof has impressed thereon the volt-

age of said source for coded intervals which are different for each of said conductors, means included in each of said links and responsive to a received series of impulses for completing a connection between one of said conductors, corresponding to the number of impulses comprising said series of impulses, and a selected called one of said subscribers' lines, means controlled by said switch for assigning a second link to search for a calling line in the event a first assigned link 10 fails to find the said calling line, means controlled by said switch for releasing a link seized by one of said lines and for preventing another of said links from being assigned to the use of said one line in the event the connector portion of the first seized link is not caused to select a called line 15 within a predetermined time interval after the link is seized, and means controlled by the control means for said switch for causing the connector portion of a seized link to search for an 20 idle one of said trunk lines on a call which is to be extended by way of one of said trunk lines. 25

2. In an automatic telephone system, a plurality of subscribers' lines, a plurality of trunk lines, a plurality of finder-connector links for setting up connections between said lines, at least a portion of said links having access to said trunk lines, allotter means for assigning said links for use in a definite order, the finder portion of each link assigned for use being effective to 30 search for and seize a calling one of said lines, a source of ringing current, a plurality of ringing current conductors each adapted to be connected to said source, a stepping switch, control means for said switch, means including said switch for controlling the connection of said conductors to said source so that each thereof has impressed thereon the voltage of said source for coded intervals which are different for each of said conductors, means included in each of said links and including a switch responsive to a received series of impulses for completing a connection between one of said conductors, corresponding to the number of impulses comprising said series of impulses, and a selected called one of said subscribers' lines, means controlled by said stepping switch for assigning a second link to search for a calling line in the event a first assigned link fails to find the calling line, and means controlled by said stepping switch for releasing a link seized by a calling one of said lines and for preventing another of said links from being assigned to the use of said one line in the event the connector portion of the seized link is not caused to select a called line within a predetermined time interval after the seizure of the first link. 40

3. In an automatic telephone system, a plurality of subscribers' lines, a plurality of trunk lines, a plurality of finder-connector links for setting up connections between said lines, at least a portion of said links having access to said trunk lines, allotter means for assigning said links for use in a definite order, the finder portion of each link assigned for use being effective to search for and seize a calling one of said lines, a source of ringing current, a plurality of ringing current conductors each adapted to be connected to said source, a switch, control means for said switch, means including said switch for controlling the connection of said conductors to said source so that each thereof has impressed thereon the voltage of said source for coded intervals which are different for each of said conductors, means included in each of said links and in- 45 50 55 60 65 70 75

cluding a switch responsive to a received series of impulses for completing a connection between one of said conductors, corresponding to the number of impulses comprising said series of impulses, and a selected called one of said subscribers' lines, and means controlled by the control means for said first-named switch for causing the connector portion of a seized link to search for an idle one of said trunk lines on a call which is to be extended by way of one of said trunk lines.

4. In an automatic telephone system, a plurality of subscribers' lines, a plurality of trunk lines, a plurality of finder-connector links for setting up connections between said lines, at least a portion of said links having access to said trunk lines, allotter means for assigning said links for use in a definite order, the finder portion of each link assigned for use being effective to search for and seize a calling one of said lines, a source of ringing current, a plurality of ringing current conductors each adapted to be connected to said source, a switch, control means for said switch, means including said switch for controlling the connection of said conductors to said source so that each thereof has impressed thereon the voltage of said source for coded intervals which are different for each of said conductors, means included in each of said links and including a switch responsive to a received series of impulses for completing a connection between one of said conductors, corresponding to the number of impulses comprising said series of impulses, and a selected called one of said subscribers' lines, means controlled by said first-named switch for releasing a link seized by a calling one of said lines and for preventing the said line from thereafter being assigned another of said links in the event the connector portion of the seized link is not caused to operate to select a called line within a predetermined time interval after seizure thereof, and means controlled by the control means for said switch for causing the connector portion of a seized link to search for an idle one of said trunk lines on a call which is to be extended by way of one of said trunk lines.

5. In an automatic telephone system, a plurality of subscribers' lines, a plurality of trunk lines, a plurality of finder-connector links for setting up connections between said lines, at least a portion of said links having access to said trunk lines, allotter means for assigning said links for use in a definite order, the finder portion of each link assigned for use being effective to search for and seize a calling one of said lines, a source of ringing current, a plurality of ringing current conductors each adapted to be connected to said source, a switch, control means for said switch, means including said switch for controlling the connection of said conductors to said source so that each thereof has impressed thereon the voltage of said source for coded intervals which are different for each of said conductors, means included in each of said links and including a switch responsive to a received series of impulses for completing a connection between one of said conductors, corresponding to the number of impulses comprising said series of impulses, and a selected called one of said subscribers' lines, and means controlled by the control means for said switch for causing the connector portion of a seized link to search for an idle one of said trunk lines on a call which is to be extended by way of one of said trunk lines.

6. In an automatic telephone system, a plu-

rality of subscribers' lines, a plurality of trunk lines, a plurality of finder-connector links for setting up connections between said lines, at least a portion of said links having access to said trunk lines, allotter means for assigning said links for use in a definite order, the finder portion of each link assigned for use being effective to search for and seize a calling one of said lines, a source of ringing current, a plurality of ringing current conductors each adapted to be connected to said source, a switch, control means for said switch, means including said switch for controlling the connection of said conductors to said source so that each thereof has impressed thereon the voltage of said source for coded intervals which are different for each of said conductors, means included in each of said links and including a switch responsive to a received series of impulses for completing a connection between one of said conductors, corresponding to the number of impulses comprising said series of impulses, and a selected called one of said subscribers' lines, and means controlled by said first-named switch for releasing a link seized by a calling one of said lines and for preventing the said line from thereafter being assigned another one of said links in the event the connector portion of the seized link is not caused to select a called line within a predetermined time interval after the link is seized.

7. In an automatic telephone system, a plurality of subscribers' lines, a plurality of trunk lines, a plurality of finder-connector links for setting up connections between said lines, at least a portion of said links having access to said trunk lines, allotter means for assigning said links for use in a definite order, the finder portion of each link assigned for use being effective to search for and seize a calling one of said lines, a source of ringing current, a plurality of ringing current conductors each adapted to be connected to said source, a switch, control means for said switch, means including said switch for controlling the connection of said conductors to said source so that each thereof has impressed thereon the voltage of said source for coded intervals which are different for each of said conductors, means included in each of said links and including a switch responsive to a received series of impulses for completing a connection between one of said conductors, corresponding to the number of impulses comprising said series of impulses, and a selected called one of said subscribers' lines, and means controlled by the control means for said switch for causing the connector portion of a seized link to search for an idle one of said trunk lines on a call which is to be extended by way of one of said trunk lines.

8. In a telephone system, a plurality of lines including a group of trunk lines, an automatic switch adapted to be seized in response to the initiation of a call on one of said lines and operative to select a desired one of said lines, said switch including means responsive to a predetermined series of received impulses for selecting said group of trunk lines, power and supervisory apparatus associated with said switch and including means operative in response to the seizure of said switch for generating interrupted ringing current, and means including at least a portion of said last-named means for causing said switch to select an idle one of said trunk lines following the operation of said first-named means.

9. In a telephone system, a plurality of lines including a group of trunk lines, a plurality of automatic switches adapted successively to be

- seized in response to the initiation of successive calls on different ones of said lines and each operative to select a desired one of said lines, each of said switches including means responsive to a predetermined series of received impulses for selecting said group of trunk lines, power and supervisory apparatus common to said switches and including means operative in response to the seizure of any one of said switches for generating interrupted ringing current, and means including at least a portion of said last-named means for causing any one of said switches to select an idle one of said trunk lines following the operation of the switch to select said group of trunk lines.
10. In a telephone system, a plurality of lines including a group of trunk lines, an automatic switch adapted to be seized in response to the initiation of a call on one of said lines and operative to select a desired one of said lines, said switch including means responsive to a predetermined series of received impulses for selecting said group of trunk lines, power and supervisory apparatus associated with said switch and including means operative in response to the seizure of said switch for generating interrupted ringing current, and means conditioned for operation by said last-named means and responsive to the operation of said first-named means for causing said switch to select an idle one of said trunk lines.
11. In a telephone system, a plurality of lines including a group of trunk lines, an automatic switch adapted to be seized in response to the initiation of a call on a calling one of said lines and operative to select a desired one of said lines, said switch including means responsive to a predetermined series of received impulses for selecting said group of trunk lines, power and supervisory apparatus associated with said switch and including means for generating interrupted ringing current, a relay adapted to be operated from one of its two positions to the other in response to the seizure of said switch, thereby to initiate the operation of said apparatus, and means responsive to the operation of said relay to said other position and effectively operative only following the operation of said first-named means to select said group of trunk lines for causing said switch to select an idle one of said trunk lines.
12. In a telephone system, a plurality of lines including a group of trunk lines, an automatic switch adapted to be seized in response to the initiation of a call on one of said lines and operative to select a desired one of said lines, said switch including means responsive to a predetermined series of received impulses for selecting said group of trunk lines, power and supervisory apparatus associated with said switch and including means operative in response to the seizure of said switch for generating interrupted ringing current, a relay adapted to be operated from one of its two positions to the other in response to the seizure of said switch, thereby to initiate the operation of said apparatus, a second relay having slow-to-operate and slow-to-release characteristics and including an operating winding, an operating circuit including said winding, said circuit being completed when said first-named relay is operated to said other positions, a path for short circuiting said winding when said second relay operates in response to its energization, whereby said second relay alternately operates and restores, and means responsive to the repeated operation of said second relay and effectively operative only following

- the operation of said first-named means to cause said switch to select said group of trunk lines for causing said switch to select an idle one of said trunk lines.
13. In a telephone system, a plurality of lines including a group of trunk lines, a line selecting switch adapted to be seized in response to the initiation of a call on one of said lines and operative to select a desired one of said lines; said selecting switch comprising a stepping switch including bank contacts arranged in sets at which the conductors of said lines terminate, wipers respectively associated with said contact sets, an operating magnet for driving said wipers, and means responsive to received impulses for repeatedly energizing said magnet to cause said wipers to be driven to a position corresponding to the first trunk line of said group of trunk lines; power and supervisory apparatus associated with said switch and including means operative in response to the seizure of said switch for generating interrupted ringing current, and means started in operation in response to the operation of said last-named means for repeatedly energizing said operating magnet to cause said stepping switch to select an idle one of said trunk lines only following the operation of said wipers to a position corresponding to the first trunk line of said group of trunk lines.
14. In a telephone system, a plurality of lines including a group of trunk lines, a line selecting switch adapted to be seized in response to the initiation of a call on one of said lines and operative to select a desired one of said lines; said selecting switch comprising a stepping switch including bank contacts arranged in sets at which the conductors of said lines terminate, wipers respectively associated with said contact sets, and means responsive to received impulses for repeatedly energizing said magnet to cause said wipers to be driven to a position corresponding to the first trunk line of said group of trunk lines; power and supervisory apparatus associated with said switch and including means for generating interrupted ringing current, a relay adapted to be operated from one of its two positions to the other in response to the seizure of said switch, thereby to initiate the operation of said apparatus, and means responsive to the operation of said relay to said other position and effectively operative only following the operation of said wipers to a position corresponding to said first trunk line for repeatedly energizing said magnet to cause said switch to step said wipers to a position corresponding to an idle one of said trunk lines.
15. In a telephone system, a plurality of lines including a group of trunk lines, a line selecting switch adapted to be seized in response to the initiation of a call on one of said lines and operative to select a desired one of said lines; said selecting switch comprising a stepping switch including bank contacts arranged in sets at which the conductors of said lines terminate, wipers respectively associated with said contact sets, and means responsive to received impulses for repeatedly energizing said magnet to cause said wipers to be driven to a position corresponding to the first trunk line of said group of trunk lines; power and supervisory apparatus associated with said switch, and including means for generating interrupted ringing current, a relay adapted to be operated from one of its two positions to the other in response to the seizure of said switch, thereby to initiate the operation of said apparatus, a second relay having slow-to-operate and slow-to-release characteristics and including an operating winding, an operating circuit including said winding, said circuit being completed when said first-named relay is operated to said

- to-release characteristics and including an operating winding, a circuit, including said winding, for energizing said second relay, said circuit being completed when said first-named relay is operated 5 to said other position, a path for short circuiting said winding when said second relay operates in response to its energization, whereby said second relay alternately operates and restores, and means operative following the operation of said stepping 10 switch to a position corresponding to said first trunk line for repeatedly energizing said magnet in accordance with the operation of said second relay until said wipers are driven to a position corresponding to an idle one of said trunk lines.
- 15 16. In an automatic telephone system, a plurality of lines, a plurality of finder switches, allotter means for assigning said switches to successive calling lines in a definite order, each of said switches, when assigned to the use of a calling line, being automatically operative to search for and seize the calling line, power and supervisory apparatus associated with said switches and including means, operative following the operation of any one of said switches to seize a calling line, 20 25 for generating interrupted ringing current, and means including at least a portion of said last-named means for assigning a second of said switches to the use of a calling one of said lines in the event the first assigned switch fails to find 30 the said one calling line.
17. In an automatic telephone system, a plurality of lines, a plurality of finder switches, allotter means for assigning said switches to successive calling lines in a definite order, each of said switches, when assigned to the use of a calling line, being automatically operative to search for and seize the calling line, power and supervisory apparatus associated with said switches; said apparatus comprising a source of ringing current, a ringing current conductor and means comprising a rotary switch for intermittently connecting said conductor to said source; means for initiating the operation of said apparatus following the operation of any one of said finder 40 switches to seize a calling line, and means including said rotary switch for assigning a second of said finder switches to the use of a calling one of said lines in the event the first assigned finder switch fails to find the said one calling line.
- 45 18. In an automatic telephone system, a plurality of lines, a plurality of finder switches, allotter means for assigning said switches to successive calling lines in a definite order, each of said switches, when assigned to the use of a calling line, being automatically operative to search for and seize the calling line, power and supervisory apparatus associated with said switches; said apparatus comprising a source of ringing current, a ringing current conductor and means comprising a rotary switch for intermittently connecting said conductor to said source; means for initiating the operation of said apparatus following the operation of any one of said finder switches to seize a calling line, a timing 50 device including a plurality of interrelated relays controlled by said rotary switch, and means included in said allotter means and responsive to the operation of said plurality of relays for assigning a second of said finder switches to the use of a calling one of said lines in the event the first assigned finder switch fails to find the calling line.
- 55 19. In an automatic telephone system, a plurality of lines, a plurality of finder switches, allotter means for assigning said switches to successive calling lines in a definite order, each of said switches, when assigned to the use of a calling line, being automatically operative to search for and seize the calling line, power and supervisory apparatus associated with said switches and including means, operative following the operation of any one of said switches to seize a calling line, a timing device including a plurality of interrelated relays controlled by said rotary switch, and means included in said allotter means and responsive to the operation of said plurality of relays for assigning a second of said finder switches to the use of a calling one of said lines in the event the first assigned finder switch fails to find the calling line.
- 60 20. In an automatic telephone system, a plurality of lines, a plurality of finder switches, allotter means for assigning said switches to successive calling lines in a definite order, each of said switches, when assigned to the use of a calling line, being automatically operative to search for and seize the calling line, power and supervisory apparatus associated with said switches; said apparatus comprising a source of ringing current, a ringing current conductor and means comprising a rotary switch for intermittently connecting said conductor to said source; a timing device including a plurality of interrelated relays, means including said rotary switch for controlling the energization of said relays, a pair of supervisory conductors, means including said relays for applying pulses of a predetermined potential to each of said conductors at spaced intervals, and means included in said allotter means and controlled by the pulses applied to said conductors for assigning a second of said finder switches to the use of a calling line in the event the first assigned finder switch fails to find the calling line.
- 65 21. In an automatic telephone system, a first line, a second line, a plurality of selector switches each adapted to be used to extend a connection from said first line to said second line, each of said switches including a link line incoming thereto and being responsive to impulses transmitted thereto over its associated link line, means responsive to the initiation of a call on said first line for connecting said first line to the link line of one of said switches, power and supervisory apparatus associated with said switches and including means, operative following the operation of said first-named means, for generating interrupted ringing current, and means including at least a portion of said last-named means for breaking the connection between said line and the link line of said one of said switches and for preventing said line from thereafter being connected to the link line of any of said switches in the event a connection is not completed to said second line within a predetermined time interval after the connection between said first 70 line and the link line of said one of said switches is established.
- 75

line and the link line of said one switch is established.

22. In an automatic telephone system, a first line, a second line, a pair of finder-selector links each adapted to be used to extend a connection from said first line to said second line, means responsive to the initiation of a call on said first line for causing the finder portion of one of said links to search for and seize said first line, the selector portion of said one link being responsive to impulses transmitted thereto over said first line, power and supervisory apparatus associated with said links and including means, operative following the operation of said one link to seize said line, for generating interrupted ringing current, and means including at least a portion of said last-named means for releasing said one link and for preventing either of said links from thereafter being assigned to the use of said first line in the event a connection is not established between said first and second lines within a predetermined time interval after said one link seizes said line.

23. In an automatic telephone system, a plurality of lines, a plurality of finder-selector links adapted to be used in setting up connections between said lines, allotter means for assigning said links to successive calling ones of said lines in a definite order, the finder portion of any link assigned to the use of a calling line being automatically operative to search for and seize the calling line and the selector portion of each link being automatically operative to select a called line in response to impulses transmitted thereto over a calling line, power and supervisory apparatus associated with said links and including means, operative following the operation of any one of said links to seize a calling line, for generating interrupted ringing current, and means including at least a portion of said last-named means for releasing a link assigned to the use of a calling one of said lines and for preventing the said one line from thereafter being assigned another of said links in the event a connection is not established by way of the selector portion of the operated link to a called line within a predetermined time interval after the operated link is taken for use.

24. In an automatic telephone system, a plurality of lines, a plurality of finder-selector links adapted to be used in setting up connections between said lines, allotter means for assigning said links to successive calling ones of said lines in a definite order, the finder portion of any links assigned to the use of a calling line being automatically operative to search for and seize the calling line and the selector portion of each link being automatically operative to select a called line in response to impulses transmitted thereto over a calling line, power and supervisory apparatus associated with said links; said apparatus comprising a source of ringing current, a ringing current conductor and means comprising a rotary switch for intermittently connecting said conductor to said source; and means including said rotary switch for releasing a link assigned to the use of a calling one of said lines and for preventing the said one line from thereafter being assigned another of said links in the event a connection is not established by way of the selector portion of the operated link to a called line within a predetermined time interval after the operated link is taken for use.

25. In an automatic telephone system, a plurality of lines, a plurality of finder-selector links

adapted to be used in setting up connections between said lines, allotter means for assigning said links to successive calling lines in a definite order, the finder portion of any link assigned to the use of a calling line being automatically operative to search for and seize the calling line and the selector portion of each link being automatically operative to select a called line in response to impulses transmitted thereto over a calling line, power and supervisory apparatus associated with said switches; said apparatus comprising a source of ringing current, a ringing current conductor and means comprising a rotary switch for intermittently connecting said conductor to said source; a timing device including a plurality of interrelated relays, means including said rotary switch for controlling the energization of said relays, a supervisory conductor, means including said relays for applying pulses of a predetermined potential to said supervisory conductor at spaced intervals, means included in each of said links and responsive to the pulses applied to said conductor for releasing the link in the event it seizes a calling one of said lines and a connection is not established by way of the selector portion of the link to a called line within a predetermined time interval after the seizure of the calling line, and line lockout means associated with each line for preventing the associated line from being assigned a link following the release of a link assigned thereto through the operation of said last-named means.

26. In a telephone system, a timing device for applying supervisory impulses of a predetermined potential to one or more supervisory conductors and comprising, in combination, a rotary switch, a first relay, a second relay, a third relay, a fourth relay, an operating circuit for each of said relays, and a holding circuit for each of said relays, said operating and holding circuits being so connected and arranged that said first relay momentarily operates to interrupt the holding circuit of said fourth relay during one operating cycle of said switch, said second relay operates to prepare the holding and operating circuits for said first relay and to complete its own locking circuit during the next succeeding operating circuit of said switch, said first relay operates to prepare the operating circuit for said third relay and to complete its own locking circuit during the second succeeding operating cycle of said switch, said third relay operates to prepare the operating circuit for said fourth relay and to complete its own locking circuit during the third succeeding operating cycle of said switch, and said fourth relay operates to open the holding circuits of the other relays and to complete its own locking circuit during the fourth succeeding operating cycle of said switch.

27. In an automatic telephone system, a plurality of subscribers' lines, means including a finder-connector link for setting up a connection between a pair of said lines, a plurality of trunk lines accessible to said link, said link including two pairs of link line conductors, one of said pairs of conductors being arranged to be included in a connection established by way of said link between two of said subscribers' lines and the other pair of conductors being arranged to be included in a connection established by way of said link and one of said trunk lines, a relay having a winding bridged across the conductors comprising said one pair, a switching relay arranged to operate when a connection is established by way of one of said trunk lines to remove

- 5 said one pair of conductors from the connection and to substitute the other pair of conductors, a ringing current source, means included in said link for completing a connection between said source and a called one of said lines selected by said link, and means for energizing said switching relay when the calling line is selected by said link on a reverting call, whereby said source is not shunted by the winding of said first-named 10 relay during the ringing operation.
- 15 28. In an automatic telephone system, a plurality of subscribers' lines, means including a finder-connector link for setting up a connection between a pair of said lines, a plurality of trunk lines accessible to said link, said link including two pairs of link line conductors, one of said pairs of conductors being arranged to be included in a connection established by way of said link between two of said subscribers' lines and the 20 other pair of conductors being arranged to be included in a connection established by way of said link and one of said trunk lines, a battery reversing relay having a winding bridged across the conductors comprising said one pair and 25 adapted to be operated when a connection is completed by way of said link between a pair of said subscribers' lines, a switching relay arranged to operate when a connection is established by way of one of said trunk lines to remove said one pair 30 of conductors from the connection and to substitute the other pair of conductors, a ringing current source, means included in said link for completing a connection between said source and a called one of said lines, and means for energizing 35 said switching relay when the calling line is selected by said link on a reverting call, whereby said source is not shunted by the winding of said battery reversing relay during the ringing operation.
- 40 29. In an automatic telephone system, a plurality of lines, a selector switch automatically operative to select a desired one of said lines, each of said lines including a pair of conductors, a plurality of ringing current conductors each adapted to have applied thereto ringing voltage 45 different in character from that applied to each of the other similar conductors, an impulse responsive switch, and means including said impulse responsive switch for selectively connecting said ringing current conductors to either of the two conductors of a line selected by said selector switch, said impulse responsive switch including contacts so connected and arranged that when a series of impulses comprising a predetermined 50 number of impulses is transmitted thereto a selected one of said ringing current conductors, corresponding to the number of impulses of said series, is connected to one of the conductors of the selected line and when said series of impulses comprises one more than said predetermined number of impulses said one ringing current conductor is connected to the other conductor of said selected line.
- 55 30. In an automatic telephone system, a plurality of lines, a telephone connected to each of said lines, means comprising an automatic switch for setting up a connection between a pair of said lines, power and supervisory apparatus comprising a pair of ringing current conductors and 60 means for applying voltages of different characteristics to said conductors, an alarm conductor normally connected to one of said ringing current conductors, means operative when a fault occurs in said apparatus for disconnecting said alarm conductor from said one ringing current conductor and for connecting 65 said alarm conductor to the other of said ringing current conductors, said switch having a position corresponding to said second line and also to said alarm conductor, means responsive to two predetermined series of impulses transmitted over 70 75
- conductor and for connecting said alarm conductor to the other of said ringing current conductors, and means including said switch for completing an alarm circuit including said alarm conductor and one of said ringing current conductors and 5 extending by way of one of said lines to the telephone connected thereto.
31. In an automatic telephone system, a plurality of lines, a telephone connected to each of said lines, means including an automatic switch 10 for setting up a connection between a pair of said lines, power and supervisory apparatus comprising a pair of ringing current conductors and means for applying voltages of different characteristics to said conductors, an alarm conductor 15 normally connected to one of said ringing current conductors, a relay including contacts for disconnecting said alarm conductor from said one ringing current conductor and operative to connect said alarm conductor to the other of said 20 ringing current conductors, a normally incomplete circuit for energizing said relay, means operative to complete said circuit when a fault occurs in said apparatus, and means including said switch for completing an alarm circuit including 25 said alarm conductor and one of said ringing current conductors and extending by way of one of said lines to the telephone connected thereto.
32. In an automatic telephone system, a plurality of lines, an automatic switch including bank 30 contacts at which said lines terminate, said lines being arranged in two groups, a line incoming to said switch, a source of supervisory current, said switch having a predetermined position corresponding to said source and to one of said plurality of lines, means responsive to two predetermined series of received impulses each comprising at least one impulse for causing said switch to operate to said predetermined position and to connect said incoming line to said one line, and 40 means responsive to one predetermined series of received impulses for causing said switch to operate to said predetermined position and to connect said incoming line to said source.
33. In an automatic telephone system, a plurality of lines, an automatic switch including bank 45 contacts at which said lines terminate, a line incoming to said switch, means responsive to two series of received impulses of which the sum total of impulses is equal to or greater than a predetermined number for causing said switch to select one of said plurality of lines, a source of supervisory tone current, and means responsive to one series of impulses comprising said predetermined 50 number of impulses for causing said switch to connect said source to the line incoming to said switch.
34. In an automatic telephone system, a plurality of lines, a telephone connected to each of said lines, means comprising an automatic switch 55 for setting up a connection between one of said lines and a second of said lines, power and supervisory apparatus comprising a pair of ringing current conductors and means for applying voltages of different characteristics to said conductors, an alarm conductor normally connected to one of said ringing current conductors, means operative when a fault occurs in said apparatus for disconnecting said alarm conductor from said one ringing current conductor and for connecting 60 said alarm conductor to the other of said ringing current conductors, said switch having a position corresponding to said second line and also to said alarm conductor, means responsive to two predetermined series of impulses transmitted over 65 70
- 75

5 said one line and each comprising at least one impulse for causing said switch to operate to said predetermined position and to establish a connection between said one line and said second line, and means responsive to one predetermined series 10 of impulses transmitted over said one line for causing said switch to operate to said predetermined position and to complete an alarm circuit including said alarm conductor and one of said ringing 15 current conductors and extending by way of said one line to the telephone connected thereto.

10 35. In an automatic telephone system, a plurality of lines, an automatic switch having bank contacts at which said lines terminate, said lines being arranged in two groups, a line incoming to said switch, a source of supervisory current, means responsive to the operation of said switch to a predetermined position for connecting said source to said incoming line, means responsive to a predetermined 20 number of received impulses for causing said switch to select one group of said lines, said last-named means being responsive to a number of received impulses greater than said predetermined number to cause said switch to operate to a position corresponding to one line of said one group of lines, means automatically operative following the operation of said switch to said last-named position for causing said switch to select the other of said groups of lines, and means 25 responsive to a number of received impulses intermediate said predetermined number and said greater number for causing said switch to operate to its said predetermined position.

25 36. In an automatic telephone system, a plurality of subscribers' lines, a group of trunk lines, a selector switch including bank contacts at which said lines terminate, a line incoming to said switch, a source of busy-tone current, said switch having a home position and a plurality of 30 off-normal positions respectively corresponding to said lines, impulse responsive means included in said switch for causing said switch to operate to a position corresponding to the first of said group of trunk lines, means only operative in the event said first trunk line is idle for operating said switch to a position corresponding to an idle one of said trunk lines, said last-named means being operative to cause said switch to return to its home position in the event all of the trunk 35

lines of said group are busy, and means responsive only to the operation of said switch to its home position by said last-named means for connecting said source of busy-tone current to the line incoming to said switch.

5

37. In an automatic telephone system, a plurality of subscribers' lines, a group of trunk lines, a connector switch including bank contacts at which said lines terminate, said subscribers' lines being arranged in two groups, a line incoming to said switch, a source of supervisory current, a source of busy-tone current, said switch having a home position and being operative to a plurality of off-normal positions certain of which correspond to certain of said lines, means responsive 15 to the operation of said switch to a predetermined off-normal position for connecting said source of supervisory current to said incoming line, means responsive to a predetermined number of received impulses for causing said switch to select one 20 group of said subscribers' lines, said last-named means being responsive to a number of received impulses greater than said predetermined number to cause said switch to operate to a position corresponding to one line of said one group of subscribers' lines, means automatically operative following the operation of said switch to said last-named position for causing said switch to select the other of said groups of subscribers' lines, means responsive to a number of received impulses 25 intermediate said predetermined number and said greater number for causing said switch to operate to its said predetermined off-normal position, said impulse responsive means being responsive to two predetermined series of received impulses to cause 30 said switch to operate to a position corresponding to the first of said group of trunk lines, means only operative in the event said first trunk line is idle for operating said switch to a position corresponding to an idle one of said trunk lines, said last-named means being operative to cause said switch to return to its home position in the event all of the trunk lines of said group are busy, and means responsive only to the operation of said switch to its home position by said last-named 35 means for connecting said source of busy-tone current to the line incoming to said switch.
